UNITED STATES PATENT OFFICE.

ANTON CHRISTENSEN, OF PHILADELPHIA, PENNSYLVANIA, ASSIGNOR TO FRANCIS T. CHAMBERS, OF PHILADELPHIA, PENNSYLVANIA, AND HARFORD W. HARE POWEL, OF NEWPORT, RHODE ISLAND.

LATHE.

1,007,065.

Specification of Letters Patent. Patented Oct. 31, 1911.

Application filed December 18, 1900. Serial No. 40,230.

To all whom it may concern:

Be it known that I, ANTON CHRISTENSEN, a subject of the King of Denmark, residing in the city and county of Philadelphia, in the State of Pennsylvania, have invented a certain new and useful Improvement in Lathes, whereof the following, reference being had to the accompanying component drawings, is a full and exact description.

10 While my invention, in many of its new and useful features, relates to lathes in general, it is especially aimed at and hereinafter specifically illustrated by a multiple reproduction lathe wherein said invention's characteristic features combine and coöperate to form a complete and improved machine.

The chief object of my invention is to provide a lathe wherein a plurality of pieces of work—each preferably like every other,—20 may be simultaneously and in synchronous progression acted upon by a plurality of similar tools. Said tools being arranged in, preferably, successively operative series, and to this end to devise and combine novel component mechanism with such drive and driven parts, including reversing, cut-out, and work and tool feed mechanisms, as will, together with my further objects, best be understood by taking this specification as a whole.

30 The new and useful features of my said invention will be found segregated in the concluding claims, and reference now being had to the aforesaid drawings, they will be found to illustrate said invention as follows:

Figure 1 is an interrupted plan view of a machine embodying by invention. Fig. 1^a is a side elevation of a detail taken therefrom. Fig. 2 is an end elevation, partially in section, of portions of said machine, the plane of section being denoted by line 2—2 of Fig. 1. Fig. 3 is an end elevation, partially in section, of portions of the machine shown in Fig. 1; the plane of section being denoted by the line 3—3 of Fig. 1. Fig. 4 is a sectional elevation of certain parts of the machine, the plane of parts sectioned being transverse to those of Figs. 2 and 3 and indicated by line 4—4 of Fig. 1. Fig. 5 is a sectional elevation of parts of the machine, the plane of parts sectioned being denoted by line 5—5 of Fig. 1. Fig. 6 is a cross sectional elevation on a larger scale of parts of said machine; the

plane of section being denoted by the line 6—6 of Fig. 1, the spectator looking toward the right or caption end of the sheet whereon said figure is displayed. Fig. 7 is a cross-sectional elevation of substantially the same parts as in Fig. 5, the plane of section being denoted by line 7—7 of Fig. 1, and the aspect and scale as in Fig. 6. Fig. 8 is a longitudinal sectional elevation of parts of said machine, the plane of section being transverse to that in Figs. 6 and 7 and denoted by the line 8—8 of Fig. 1, the scale as in Fig. 6. A subsidiary driving device, shown in Figs. 1 and 6, being omitted to prevent overcrowding of lines. Fig. 9 is a longitudinal elevation sectioned in details upon line 9—9 of Fig. 10; it shows parts of the machine denominated the mandrel's component; the scale being as in Fig. 6. Fig. 10 is an end elevation of said component, fragmented; it is transverse to Fig. 9 and on same scale. Fig. 11 is a longitudinal, in part sectional, detail fragmented from the drive stock component; the scale being still more enlarged. Fig. 12 is an enlarged scale 80 fragmented detail, generally in longitudinal section, of the drive stock aforesaid. Fig. 13 is an end elevation upon an enlarged scale showing details of a preferred tool holding turret. Fig. 14 is a side view, 85 partially in vertical section, of the mechanism shown in Fig. 13, the plane of section being denoted by line 14—14 of Fig. 13. Figs. 15 and 16 are respectively front view 90 and side elevation of a modification of detail from a part denominated the puppet component. Fig. 17 is an enlarged plan view, partially in section, of a device fragmented from and ancillary to the mandrel's component aforesaid, and Fig. 18 is an end 95 view, partially in section, on the line 18—18 and of parts shown in Fig. 17.

For convenience of description, the machine will be named and developed as follows: First, the live stock component; second, the mandrel's component, and, third, the tool carriage or puppet component: the frame, guideways, intermeshing mechanisms, and certain ancillary devices incident thereto, being relied upon to evidence 100 that connection between said components which combines the three of them into a co-operating and nicely interacting whole.

Beginning with the live stock aforesaid, A', A² A³ are parallel frames fixed to and 110

rising at right angles from the main horizontal bed A. This bed may be any suitable foundation, preferably, a heavy integral slab of cast iron and, in plan, of the general outline of the machine, see A, Fig. 1. Within the upright frames A' A² are journaled shafts S' S² etc. All of these shafts lie parallel, and, so far as the live-stock is concerned, are presumably endwise collared and equipped as follows: Upon shaft S' there is fixed a main belt wheel s. This wheel is the principal point of application of power, derivable from any suitable countershaft, yet one having, preferably, the ordinary cut-out and reversible rotary movements. Upon said shaft S' there is also mounted with freedom for angular movement, but, by the lateral interlock of the gears which it embraces an endwise collared chair C. This chair bridges a pair of gears g g', Fig. 11. These gears, are fixed to and carried by shaft S', and gear respectively with pinion gears g² g⁵ formed as integral hub-parts on two otherwise independent spur gears g³ g⁴. These latter gears g³ g² and g⁵ g⁴ are mounted rotatively loose on a countershaft s' fixed in the cheeks of said chair C. As the spur gear g' is less, say by one half its number of teeth, than is its adjoining spur gear g, it is clear that the gears g³ g² and g⁴ g⁵ will be driven at different speeds on the rotation of shaft S'; also as the gears g g' are fixed to said shaft S', that they act laterally to collar said chair as aforesaid.

By means of a throw rod c, Figs. 6 and 7, pivoted to a lug c' on chair C said chair may be swung about shaft S' and bring any one of gears g³ g² g⁴ g⁵ into meshing reach of a pinion gear d. This latter gear, mounted with freedom for endwise sliding upon a shaft S², is, see Fig. 12, first rotatively engaged thereto by its own slotted eye d⁹, a spline d', and said spline's shaft seat s²; and, second, laterally controllable as follows:—said spline d' having shoulders embracing sides of gear d by an extension d⁵ which extension in the section conforms to the metal presumably removed in making the seat s²—can be moved along said seat in proportion to the total length of the gears g³ g² and g⁵ g⁴ aforesaid. For this purpose said extension d⁵ of the spline d' extends without detriment to the rotary movement of shaft S², out through said shaft's bearing, a¹⁹, in the frame A', see Fig. 1, and there, by other shoulders d² d³, Fig. 12, engages the ends of a collar d'. This collar fitted to slide endwise on the shaft S² (which shaft revolves free in said collar's eye d', Fig. 12,) is pivoted at d⁷ to one end of a shifter lever D; and this lever, pivoted at a⁵⁰, see Fig. 1, upon a bracket a⁶⁰, thence extends one of its ends to what I shall designate the operating angle Y of

the machine, and is there shaped to a handle. Bracket a⁶⁰ is fixed to frame A'.

By control of shifter lever D and throw rod c the shaft S² can be cut out; or, being thrown in gear, given four different speeds, as follows: of said gears g' g² g⁴ being say of thirty-two teeth each and gears g g³ g⁵ and d being of sixty-four teeth, then if shaft S' makes three hundred revolutions, see Fig. 11, and gear d is meshed with gear g³ shaft S² will make six hundred revolutions; while if gear d is geared with gear g² said shaft will make three hundred revolutions; so gears g⁵ and d give one hundred and fifty and gears g⁴ and d seventy five revolutions to shaft S². Postponing description of the functions of shaft S² (so controllably subject to changes of speed) in so far as the same are made use of without the live-stock, and passing now to said shaft's further connections within said live-stock. Motion also can be taken off from, or (gear d being disconnected, by manipulation of throw rod c, from gears g³ g² g⁵ g⁴) received by, said shaft S² by way of a spur gear d⁸ (Fig. 1). This gear d⁸ is fixed on said shaft S² and is controllably meshed with one or other of a pair of gears e³ e⁴ forming part of a revolution reversing device. This device, see Fig. 6, consists of vibrating apron E provided with (1) an operating handle e and (2) laterally projecting studs e' e²; upon these studs are mounted loose stud intermeshing gears e³ e⁴ of say thirty two teeth each, and so located that by vibrating apron E about its pivot s⁴ (which pivot at one end is fixed in the frame A²) either one of the gears e³, e⁴, can be engaged at will with gear d⁸ aforesaid; and further the gears e³ e⁴ are so located on apron E that one of them, e³, not only meshes constantly with the other, e⁴, but also with a gear E'. This latter gear is mounted loose on the stud s⁴ upon which the apron E also is mounted as aforesaid; and of which apron E, it may be here noted that a gap or open arc slot e⁵ on its bottom part straddles over the shaft S² aforesaid and acts, with the laterally adjoining faces of frame A² and gear d⁸, as a steady guide useful when the apron is vibrated, while the bottom, e⁵⁰, of said gap affords, when gears e³ and d⁸ are meshed "to pitch" line, a convenient stop by banking on shaft S². But to continue, concentric with and attached to gear E' there is a small gear e⁷ (see Figs. 1 and 6). Motion is taken off from this gear e⁷ by a gear E² (Fig. 8) fixed to one end of a sleeve E³, which sleeve carries fixed to its other end a gear E⁴ and is, carrying said gears E² E⁴ journaled loose, on shaft S⁴. Through said gear E⁴ intermeshing with a back gear train, next to be described, any rotary motions it receives are imparted to a pinion gear K. Pinion K is fixed to shaft S⁴ and when actuated drives it; or the

reverse. Said back gear train consists of pinion gear e^8 and spur gear e^9 (Fig. 8) both fixed to a small shaft s^5 , that is, journaled parallel to the other shafts in housings A^2 A^3 . In driving from belt wheel s through apron E the function of this back gear of which this small spur e^9 meshes with said larger pinion K is, as usual in lathe back gears, to reduce speed and give a more 10 powerful drive motion to the shaft S^4 .

The shaft S^4 , being a factor in the mechanism employed when the lathe is adapted to cutting screw threads, is further, for this purpose, geared and connected as follows:

15 Upon mid body of said shaft S^4 there is journaled a normally "loose" vibrating lever k (see Fig. 7). To the lever k at its fulcrum eye k^{22} (Fig. 8) there is collared laterally a spur gear k' . This lateral collaring 20 and also the rotative engagement of said gear to the shaft S^4 , on which it, too, is mounted, is conveniently accomplished as follows:—a slot k^{21} is sunk lengthwise along shaft S^4 , and, fitting therein for endwise sliding, 25 works a spline k^{20} (see also Fig. 7); this spline projects part of its body into the registering eye-slot (not lettered to avoid confusion of lines) of gear k' , and by terminal shoulders k^{18} k^{19} —the latter carried on an 30 extension of said spline which exactly conforms to any section of said shaft slot k^{21} that may underlie the eye k^{22} of lever k —laterally engages said lever and gear together. Thus equipped the spur k' meshes 35 with and, if rotating under control of hand parts D c E aforesaid, drives a subsidiary spur k^2 . Spur k^2 is mounted upon a pin k^3 fixed to one side of the short arm of lever k aforesaid. Lever k at its opposite end is 40 formed with a downwardly cranked part k^4 adapted, when traveled along the shaft S^4 , to ride on inclined rail a . This rail is fixed strutwise to and between the front ends of housings A' A^2 and being dropped sufficiently to clear spur k^2 , when traveled along 45 shaft S^4 , is also sloped in accordance with the gain in diameter of a series of progressively increasing gears soon to be mentioned. In the crank part k^4 of lever k there is 50 threaded a set screw k^5 adapted, by being "set" on the side of said rail a , to hold said lever arm in the position shown in Fig. 7, or in such similar positions along rail a as causes the subsidiary spur gear k^2 to register and intermesh with the several members of the progressively increasing series 55 of gears k^5 to k^{18} , inclusive, that are fixed to shaft S^3 . This shaft S^3 is also journaled, parallel to all the other shafts, in the housings A' A^2 of the live stock, and carries mounted on it the aforesaid progressive gears, which gears being of say 32, 36, 40, 44, 46, 48, 52, 56 and 64 teeth, give with a "two to the inch" pitch lead screw (herein- 60 after mentioned) the usual variations in

speed appropriate for work and tool in screw cutting lathes. These variable speeds of rotation of the shafts S^4 , thus transmitted by gears k^2 as well as those derivable to same shaft S^4 from shaft S' —through the various speed controls of lever D and throw rod c , reversing apron E , spur e^7 , sleeve gears E^2 E^4 , back gear train e^8 e^9 and pinion K are arranged to be taken off and transmitted to the other parts of the lathe as follows: 70 Upon the shaft S^3 (see Fig. 6) there is mounted, with freedom for angular movement about such shaft as a pivot, a second chair C^2 . This chair straddles, (see Fig. 8,) gears k^{14} k^{15} of say 32 and 64 teeth respectively, both of which, being fixed to shaft S^3 are rotated by it; and meshing, with, drive two independent change of speed trains. These trains consist of four gears l — l' and l^2 — l^3 fixed in couples as hyphened, but each couple free of the other, and loosely journaled upon a countershaft s^3 fixed in the chops of said chair C^2 . Each of said gear couples being of say 64 and 32 teeth, they are, together with their chair C^2 , collared 80 by the "free" but lateral interlacing of the gears k^{14} and k^{15} which, gears intermeshing with the gears l^3 and l respectively as aforesaid, are fixed to shaft S . This mechanism produces changes of speed in any shaft to 85 which it may be coupled by a single gear analogous to the changes produced by the gearings of chair C aforesaid with pinion gear d on shaft S^2 . Of course the speeds and movements of rotation which shaft S^3 90 may receive from said shaft S^2 , by way of the hereinbefore described intermediate gearings are very various but at the same time so obvious as not here to require further statement. So equipped and speedable the gears l — l' and l^2 — l^3 of chair C^2 95 are adapted to have their motions taken off as follows:

A throw rod c^2 is pivoted (see Fig. 6), to a lug c^3 , extending downward from one of the chops of said chair. Thence said rod c^2 passes outward, rests on a shaft S^7 and terminates in a handle located near the angle of operating Y , Fig. 1. This rod c^2 being pulled outward it is possible to vibrate and hold any one of the said four gears l — l' l^2 — l^3 in mesh with a longitudinally slidable pinion gear F (see Fig. 7). This gear F mounted on a shaft s^{30} carries a spline f working in a slot f' (Fig. 5) sunk lengthwise along said shaft and so acts to drive said shaft S^5 at any point in its range thereon. The gear F is mounted for convenient use between the tines f^2 f^3 (Figs. 1 and 7) of a straddling manual fork F' ; and said 110 fork, being provided with a handle part f^4 , is adapted to bank on, but slide longitudinally along, a horizontal tie a' fixed to and extending between the frame parts A^2 A^3 aforesaid. By coöperation of fork F' and 115 120 125 130

throw rod c^2 the gear F may be meshed with any of the four gears $l-l' l^2-l^3$, and, by its spline f , drive the shaft s^{30} . And the shaft s^{30} by the medium of an endwise slidable but 5 rotatively splined clutch L—see its spline L^{11} in end view Fig. 6—is reversibly connectable, or disconnectable, at will to the shaft S^5 , as follows:—(1) by a gear l^5 , having (Fig. 8) clutch engaging parts l^9 with 10 reverse motion to a gear s^{18} , and (2) by a gear l^4 having clutch engaging parts l^8 to an intermediate idler gear mounted loose on stud l^{20} that projects horizontally from frame A^2 and thereby, with direct motion, 15 to gear s^{19} ; which latter gear with the gear s^{18} aforesaid are both fixed to and according to their engagement clutch L with them drive forward or in reverse the shaft S^5 . To which end the clutch gears $l^4 l^5$ aforesaid, mounted rotatively loose on shaft s^{30} , 20 are presumably collared against endwise motion along the same and localized at the range limit of the sliding clutch L: which clutch in its intermediate position (depicted 25 in Fig. 8) is free of both said clutch gears $l^4 l^5$, but is adapted to be moved therefrom into engagement with the gear clutch parts $l^8 l^9$ by the cylindriform inner ends $l^6 l^7$ of, a forked shifter lever L' . For which purpose 30 said ends straddle said clutches reduced mid body l^{10} in the usual manner, and the lever L' , pivoted for horizontal swinging to a bracket a^{40} formed on inner cheek of frame A^3 , thence projects its operating handle out 35 near to the hand parts of the shifters aforesaid (see Figs. 1 and 6).

The shaft S^5 so connectible and subject at will to various speeds of controlled rotation—due to the above described mechanisms 40 of the live-stock is utilized in screw and volute turning as the driver for (1) “traversing” the mandrel's component, (2) advancing or retreating or stopping the puppet component. But before passing to a 45 description of these functions etc., other features of my preferred live-stock are to be specified, viz: For the purpose of actuating shaft S^5 and the parts which it ultimately controls, independent of the already above 50 described mechanisms which, at least primarily, are adapted to receive motion from the main belt wheel s (and wherein the shaft S^2 is, as later set forth herein, the chief live-stock driver for the mandrel's component) I also provide and combine in the live stock, preferably two, other drive motions. 55 Of these motions I shall designate one as the direct or “handy-jack” and the other as the ordinary “turning drive motion” of 60 the shaft S^5 ; while for that which already described connects it operatively with the shaft S^2 aforesaid, I shall employ the designation of “compound screw” or “mandrel's-carriage-puppet-drive-motion.” Taking now 65 the said ordinary “turning drive mo-

tion” of the shaft S^5 , and referring to Figs. 1, 5, 7 and 8, it will be seen in the illustrative case to consist of the following mechanism: Upon the shaft s^{30} there are, in addition to the mechanisms already described, mounted between frames $A' A^3$ two presumably endwise collared loose gears $b' b^2$; these gears are provided, each on their like adjoining ends, with clutch members $b^{20} b^{21}$; between these I locate a rotatively engaged but endwise slidable clutch sleeve b which sleeve, being provided with the usual clutch engaging ends for interacting with said clutch parts of gears b' and b^2 aforesaid, is centrally grooved and thereby engages with the pins $b^3 b^4$ (Fig. 8) of a forked operating lever B (Fig. 1) pivoted to a bracket a^5 , Fig. 1, of frame A' . By engaging this clutch aforesaid with gear b' (of say 64 teeth) motion can be taken off from a gear B' of similar size fixed in range on a shaft S^7 ; of which shaft more will be said hereafter. This latter gear B' is also meshed with a small gear b^{10} , see Fig. 7, fixed on shaft s^6 ; which shaft, journaled in frames $A' A^3$, is, outside frame A' , provided with a fixed independently actuatable belt wheel s^7 , see Figs. 1 and 8. Of these parts the clutch b , placed in intermediate position, both gears $b' b^2$ lie at rest; or else said clutch, thrown by hand lever B aforesaid into engagement with gear b' (of say 64 teeth) then said gear and shaft S^7 , to which it is thus temporarily engaged, are driven at equal speed but in opposite directions: 100 so with clutch b engaged with gear b^2 and driven by shaft s^{30} , as said gear b^{20} meshes with an intermediate idler gear b^8 journaled loose upon a stud p^{11} fixed to project horizontally from frame A' and, as across the 105 said idler (which therefore acts to reverse the motion) there is also meshed therewith a spur gear b^9 of say 32 teeth which gear is fixed to shaft S^7 —there is given to said shaft S^7 a reverse motion one half slower than the relatively speaking forward motion producible by the first described clutching of clutch b . Also by using a reversing and stop motion counter shaft—as 110 is well understood in the belting of lathe drive pulleys, a reversing motion and stops and starts—may be controllably given to either the pulleys $s s^7$ and thereby the effect of the clutches b and L aforesaid made the reverse of those now described; but, as this trenches upon matter understood by engineers, it is to be indicated and not herein more fully described. In addition to thus causing the shaft S^7 to revolve in either direction or else to lie at rest, it is obvious 115 from inspection of Figs. 7 and 8 that whenever the shaft s^{30} is so driven from the belt wheel s^7 , and the clutch L is thrown into engagement with either the clutch parts $l^8 l^9$ of the gears $l^4 l^5$, that the shaft S^5 will be 120 125 130

driven as above described by the gears (l^5) l^{20} s^{19} ; or by (l^5) s^{18} aforesaid. That is to say, shaft S^5 can with throw rod c^2 cutting out its gear trains and, therefore, also cutting out from S^5 shaft S^2 —be driven, by way of shaft S^7 , by shaft s^6 and belt wheel s^7 . It is proper also to note at this point that as hereinafter more particularly described shaft S^7 is the direct live-stock

10 driver of the puppet proper.

10 The direct or "handy-jack" drive motion above alluded to consists of a gear d^{10} , Fig. 6, fixed to another independently actuatable shaft S^8 ; which latter shaft, journaled in frames A^2 A^3 , also projects from the frame A^8 , and there (Fig. 1) has fixed on it a belt wheel d^{11} ; which wheel, like the belt wheel s^7 , is presumably belted to an independently controlled and actuated countershaft. This 15 mechanism (belt wheel d^{11} , shaft S^8 and spur d^{10}) serves to drive shaft S^5 independently of both the above described main trains of the live-stock; and is designed to be used when said main trains are cut-out, and, then, 20 to effect quick traverse movements in certain parts next to be described, as the "mandrel's" and "puppet components."

Passing temporarily from the live-stock, said "mandrel's component" consists of (1) 25 a carriage M , in form a lidless bottomless box, which has on the bottoms of its sides, guide parts m^7 m^8 fitting slidingly upon ways a^4 a^5 , and the latter formed in the tops of web shears A^4 A^5 which, integral with 30 bed A , lie parallel and in line ahead of the live stock; and (2) said carriage's equipment: This equipment consists of a series of mandrels N N' to say N^5 , all alike and each, preferably, as illustrated in the figures, of the "sliding" variety. The front and tail bearings for these mandrels are located in the sides of the carriage M (see, as illustrative of all the cylindrical bearings m m' carrying with sliding freedom 35 the mandrel N^5 in Fig. 10). But said mandrels and their respective bearings being in general not otherwise than is familiar in lathe construction are not herein further illustrated or described, save only 40 where the mandrels N N' , etc., project beyond their tail bearings (m' of mandrel N^5) to the rear, they are each provided with abutments, preferably of the following character, viz: Between collars n n' , fixed 45 to said tail of each mandrel there are mounted, see Figs. 9 and 10, so as to be rotatively free on each of said mandrel's tails, a washer n^2 and a forcing sleeve n^3 . These sleeves are each provided with an engaging 50 part, viz: the pins n^4 fixed thereto; which pins project into slots h (Fig. 10) formed in the bent pendant arms h' hanging down on one side of forked levers H . These levers H , whose shape will be 55 observed by viewing Figs. 1, 9 and 10 in con-

junction, are attached by pivot pins n^4 to brackets m^2 m^2 (secured in pairs astride each of the mandrel tails aforesaid and to carriage side m^3), and have each, upon their outstretched arms h^2 a weight H' 60 (see Figs. 1, 2 and 3). These weights are mounted say by snug fitting eye h^3 , (Figs. 2, 3) that they may be slid manually lengthwise along said arms h^2 , or be left thereon, even when the machine is "at work," at any 65 point of their travel and "stay put." The abutment thus afforded the mandrels is of a yielding yet resilient nature, the intensity of which is determinable by either the amount of said weights H' , the positions of 70 said weights on the arms h^2 or, although this departure from uniform arrangements is not preferred, by combinations of various weights and various arm positions. In any 75 of these arrangements the effect of this preferred mandrel abutment is to tend to hold the collars n^3 up to the rear face of their proper mandrel tail bearings, and to cause the mandrel nose or work engaging end of each said mandrels N — N^5 to tend to 80 protrude to its maximum. Therefore while each mandrel yields according to the exigencies of its proper piece of work, all may ultimately come to a uniform protrusion and none surpass it. But in order at times 85 otherwise to limit the mandrel's protrusion or sliding I also preferably provide each and every said mandrel with an adjustable stop. Such stop is illustrated in Figs. 2 and 3 by a screw I engaging in a hole (not lettered to avoid confusion of lines) tapped through back side m^3 of carriage M ; whence each said screws I protrudes and exposes 90 its point in range of its proper downward hanging lever arm h' of the forked levers 95 H aforesaid. An extension i of said screw's shank being passed through a suitable aperture (also for similar reason unlettered) in line in the opposite carriage wall m^4 —thence also protrudes and is provided with 100 any convenient manipulating device; such as handwheel i^2 , Fig. 10. By means of these stop screws any less and adjustably determinable degree of mandrel protrusion may be established with both nicety and convenience. This despite the fact that usually 105 they are all to be adjusted alike.

Returning to the main description. The nose or "business end" of each mandrel is presumably equipped with the usual work 110 engaging device of a lathe, illustrated in Figs. 1, 2, 3 and 9 and 16, by the three-jaw chucks O . And, while the means for transferring motion to said mandrels may, without departure from the general invention, be any, yet I prefer to use, and specifically claim herein, the mode illustrated in the drawings, to wit: a pinion gear o fixed to each said mandrels (as by being formed 115 on the periphery of the mandrel nose flange 120

125 130

o'), and by intermeshing therewith a spur gear o^2 carried on a shaft o^3 journaled in carriage sides m^4 m^5 (see Fig. 2). Each said shaft, o^3 , has on its rearward protruding part, a fixed bevel gear o^4 ; and each of these gears o^4 meshes with a corresponding bevel gear o^5 each collared to and journaled in a bracket M' located on the back, m^3 , of carriage M . This collaring is indicated in Figs. 9 and 10 where the gears o^5 have tubular hub extensions o^6 journaled in said brackets, and collars o^7 fixed to said hub extension ends. The controllably speeded shaft S^2 , aforesaid, extends out from the live stock and passes endwise freely through each of the bevel gears o^5 but is (by spline seats s^{11} and spline o^8 (Fig. 10) fixed in each of said gear's eyes) rotatively attached to said gears. By this means the shaft S^2 connects the mandrels N — N^5 operatively with said live stock; and, subject to its organization and control (above described) imparts or denies motion to said mandrels; in fact, is the chief member of said mandrel's "motion."

Reciprocally to move; or, when not in motion along the ways aforesaid, to hold the carriage M , I provide on a prolongation of the shaft S^5 , that extends from the frame A^2 to and through the carriage M (see Figs. 1, 2, 3, 9 and 10) a screw part S^{10} whereof the threads coöperate with a nut, preferably of the disengageable "split" type, illustrated in Figs. 1, 1^a and 2 by the handle provided half nut S^{11} . This nut is pivoted at a^6 to carriage end m and swings in range of said screw part S^{10} of shaft S^5 . By this means, when the half nut S^{11} is engaged on the screw part S^{10} , if the shaft whereon said screw is formed is at rest, the carriage M is locked; or, if said screwed shaft S^5 be forcibly rotated, the carriage M is thereby moved according to (1) the direction of the thread on said shaft, and, (2) the controlled motions of said shaft; which motions are then imparted to the carriage by nut S^{11} . Now the thread S^{10} of this, in part, screwed shaft S^5 being of say two to the inch pitch, and the shaft itself connected to and controlled by the gear trains, clutches, and so forth of the live stock and said gears toothed and proportioned as aforesaid, it is obvious that many reciprocal movements, stops, starts, and so forth can be given to the carriage M ; and these controls and motions can be effected at will, either independent of, or for screw, volute, etc., cutting incident to and synchronous with, the mandrel motions derivable through the shaft S^2 ; the whole being under the control of the shifter levers and throw rods of the live stock as aforesaid. And this so long as the split nut S^{11} is engaged on its screw S^{10} . But should said nut be disengaged therefrom the carriage M

may be moved either (1) by hand, or (2) mechanically as hereinafter soon to be explained.

By these means many desirable functions heretofore only to be had independently, in independent lathes, are, by my invention, embodied in a series of mandrels combined in a multiple mandrel's component.

To keep the mandrel's carriage M from lifting, besides its own weight and that of its equipment, which weights together may be sufficient so to keep it, I prefer to keep it down positively. This is illustrated by the end view of L-shaped clips a^{30} a^{31} , Fig. 2; which clips bolted to shears A^5 A^4 are removable, for assembling, etc., but being fixed in place extend their L's over corresponding L shaped and (to permit the sliding of carriage M) faced upper flanges of said carriage's bottom guide parts, m^8 m^9 , respectively, and thereby keeps said carriage to place on the bedways a^5 a^4 . The shaft S^5 also passes freely through apertures, (not lettered to prevent overcrowding of lines) formed in the ends of carriages M , and finds, beyond the limits of the ways a^4 a^5 (Fig. 2) a further bearing in a terminal vertical frame A^6 . Beyond this bearing the shaft S^5 again protrudes and carries fixed to it a spur gear Q . This gear (see Figs. 1, 9 and 10) meshes with one or other of two intermeshing pinions Q' Q^2 journaled to studs q q' fixed laterally in a vibrating apron Q^3 . Said apron, being pivoted to frame A^6 at Q^5 , is provided with a handle and a slot and set screw clamping device; whereof Q^6 is the slot, and Q^7 the headed set screw, which passing its shank through said slot, threads into the adjacent wall of frame A^6 . By swinging and clamping with screw Q^7 this apron it is obvious the rotary motion of shaft S^5 will be (at increased speed) imparted to the gear q^8 ; which gear is mounted loose on said apron's pivot. Now this gear q^8 which also meshes with gear Q^2 aforesaid has fixed to it a large concentric spur gear q^9 of say sixty four teeth; and the latter gear (q^9) meshes with a pinion q^{10} of an equal number of teeth which is mounted freely on a pivot q^{11} fixed in a second vibrating apron Q^8 . Said second apron (being pivoted, see Fig. 10, on a protruding part of the puppet's component lead screws shaft, S^7) is provided, by way of a clamping device, with a pivot centered circular arc slot q^{12} and a shoulered stud q^{13} . Which stud screwed into frame A^6 , thence extends and, passing its reduced part through said apron slot, carries on its threaded outer end a clamping nut q^{14} . There is also preferably formed integral on said apron Q^8 a handle q^{15} by which the apron can be swung manually to bring its gear q^{10} in or out of mesh with the gear q^9 aforesaid; and, in either of said

positions, said apron Q^s can be clamped and kept to place by the nut q^{14} aforesaid. Fixed to the pinion q^{10} , and therefore carried with it, is a smaller gear q^{16} —of say thirty two teeth; this gear meshes permanently with a gear q^{17} fixed on the outer end of the shaft S^7 ; which shaft, as herein-after described, actuates the puppet motion screws. It is obvious that, if by the manipulation of apron Q^s and clamp nut q^{14} , this gear q^{17} fixed on the end of shaft S^7 is operatively connected with the gearing aforesaid connecting with shaft S^5 , that shaft S^7 may be thereby driven in either direction; or by relaxing nut q^{14} and swinging out of mesh the gear q^9 q^{10} carried on the aprons Q^3 Q^s respectively, the shafts S^5 S^7 will be cut out from each other. That is to say, as a combinable element the apron Q^3 and its gears constitute a reversing change of motion device, and the apron Q^s with its gears a cut-out device. They belong to the live-head-puppet transmitting mechanisms. The diameters and relation of the gears upon these aprons is such (as will be seen by inspection of Figs. 9 and 10) that when shaft S^5 drives the shaft S^7 forward (or in the direction indicated by curved arrows in Fig. 10) an equal speed will be given: but when reversed by dropping apron Q^3 as gear Q^2 is smaller than gear Q^7 a reverse and slightly reduced speed will result to shaft S^7 .

The shaft S^7 is journaled not only in framing of the live stock, as aforesaid, but also extends to, passes through and finds a bearing in the terminal frame A^6 aforesaid. Between the frames A^2 and A^6 the shaft S^7 has fixed upon it, see Figs. 1 and 2, two equal bevel gears r r' . These gears mesh with duplicate bevel gears r^2 r^3 , of say twice their number of teeth. The latter gears are fixed as heads upon duplicate transverse screws T T' ; which screws have short unthreaded shanks t^6 t^7 journaled in the bed shear A^4 with endwise abutting collars as t t' of the near screw T' in Figs. 2 and 3. Said screws thence extend, lie parallel to each other, and engage in nuts t^2 t^3 fixed, as shown in Figs. 2 and 4, to the front crosstie p^2 of the puppet component. By these connections the screws T T' can be cut out from or given all the speeds and back and forth rotary motions possible to the shaft S^7 ; which shaft being driven, drives them, or left at rest suffers the endwise collared screws T T' engaged in their nuts t t' to act as a locking device and so hold the puppet P at any point of its travel.

Passing now to the third chief element of the invention—the puppet, and referring to Figs. 1, 2 and 3, it will be seen to consist of a chair P having substantially triangular end housings p p' (Fig. 1) and crosstie bars p^2 p^3 fixed as by bolting (see Fig. 2) to and

uniting the lower corners of said end housings, so that the whole constitutes a substantially chair like form. This chair P has, centrally located and journaled across it, a substantial pivot P' . Upon this pivot P' I mount a reel U the shape of which will be grasped by taking Figs. 1, 2, 3 and 4, in connection; and it will be seen to consist of a series of similar webbed sections U^{20} U^{24} ; the general form of each of which sections is plainly shown by the elevation of the two of them which lie farthest from the live stock aforesaid, in Figs. 2 and 3. Each of these sections U^{20} to U^{24} see Fig. 4 carries on its four arm like extensions u a share of the parts supporting the lathe's tools. This is accomplished in the illustrative case by fixing the reel section U^{20} to U^{24} , see Figs. 1, 2, 3, and 4, to each other by pin shafts P^2 P^3 P^4 P^5 . Therein these shafts are located parallel to themselves and to and at equal radii from, the main pivot P' ; they are also spaced at 90° to each other. In the illustrative case, at least, the ends of these pin shafts protrude from the terminal reel sections U^{20} and U^{24} , and carry on each such end, as well as on their sections lying between every reel section, a tool holder. These tool holders I preferably make alike and in the form of the turrets U' of Figs. 1, 2, 3 and 4, etc. While such turrets U' may, in general, be of the construction and have the scope or functions familiar to those conversant with turret lathe mechanisms, and therefore not necessary to be herein further described, yet in Figs. 13 and 14, I have shown such a form thereof as I have contrived with special reference to and found best suited for my present invention: a hexagonal disk U' adjustably fixed by a central eye u^2 , wedge u' , and key way u^3 to the pin shafts P^2 — P^5 aforesaid: Also in the central plane, and, preferably, in radial and equal angular arrangement, of each said disk I form a series of tool sockets u^4 : Into these sockets on one side I bore (Fig. 14) a secant cylindrical chamber u^5 so that each of said chambers at its bottom, merges into a concentric tapped hole u^6 , and then, by a "headed" and washer provided, binding screw, u^7 , I force a binding tube section, u^8 , down upon any registering cylindrical tool or tool holder shanks, u^9 u^{10} , respectively as may be fitted to and placed in each of said sockets. By these means I bind said tool or tool holder shanks u^9 or u^{10} to the preferred turrets U' with such longitudinal protrusion, angular position or "setting" that may be desired (see Figs. 13 and 14 respectively).

To bring the various tools in registering conformity with the proper mandrels, each turret may be adjusted longitudinally on its supporting pin shaft as shown in Fig. 1, where the portion of the pin shaft P^4 adjacent one of the mandrels is shown as pro-

vided with threads J. The corresponding turret U⁴ being clamped in place between nuts j' and j² locked in position by jam-nuts j and j³. While in order to avoid confusion of the drawings I have only shown one of the turrets as longitudinally adjustable upon its supporting pin shaft, it will readily be understood that all, or as many as desired of the turrets may be made so adjustable.

10 In order the better to contact the binding tube sections u⁸ aforesaid upon the tool or tool holder shanks I preferably project said tube binding sections initially somewhat far down their respective chambers, and, by 15 a boring operation, chamfer off a small cove, as u¹¹, Fig. 14, from the edges thereof.

To rotate the tool holder U I provide, preferably on the live stock adjoining end of the main pivot P', a fixed gear V. This gear 20 meshes with a spur gear V' carried fixed on a crank shaft v which, provided with a crank handle v', is journaled between the puppet chair's adjoining end plate p and a small bracket v² bolted thereto. By means 25 of this handy device (the shaft v of which is adapted to slide endwise through its bearings) the operator can either (1) rotate the reel U until some one of the tool turrets aforesaid comes opposite, say the axis line 30 of the mandrel noses in the mandrel's component M, or else (2) by endlong sliding of the crank shaft v (and after its spur gear V' disengages from the gear V) fetch another gear V² (located upon and fixed to an 35 inwardly protruding end of said crank shaft v) into mesh with one, see Fig. 1, of a series of equal pinions V³ that are fixed to the ends of the reel pin shafts P² to P⁵ aforesaid. Such engagement of the spur V² 40 (carried on the inner end of the crank shaft v, as indicated in broken line at V², Fig. 1) is possible when any one of the pin shafts P²—P⁵ is brought with its gear V³ in range thereof. By this latter means not only any 45 desired one of the ranks of the turrets or tool supporting parts U' carried in the puppet reel U can be brought opposite to the line of mandrels carried in the carriage M, but the tools T¹⁰ or tool holders T¹¹ fixed in 50 said turrets, see Figs. 1, 5 and 13, can be presented thereto in series as said turrets are, in turn revolved through successive angles of 60° each.

In order to hold the turrets U' and reel U 55 in such postures of tool presentation to the mandrels N—N⁵ I provide upon each of the pin shafts aforesaid (that carry the turrets) a fixed, and in this case, hexagonal prisms X X' see Figs. 1, 2, 3, 15 and 16; 60 and, for engagement with these prisms, I provide a correspondingly gabbed spanner or spanners x x' fixed in appropriate alinement upon a rock shaft x². This shaft journaled to lugs p⁶ p¹⁰ integral on the pup- 65 pet's tie p², and end plate p respectively,

projects, one end, preferably that on the live stock side, and is there provided with a transverse hand rock lever X². The reach to these prisms X X' and the position of their facets being in conformity to those of 70 their ranks or turrets U (Figs. 2, 3) it is obvious that the spanners x x' may be rocked by manipulation of said rock-lever and thereby either be engaged upon or cleared from their respective prisms X X'. Cleared 75 of them the reel U and all its turrets can be normally revolved: engaged the said spanners hold the same. But, where great steadiness is required in the holding of the reel U and turrets U' which steadiness is 80 generally essential to the mandrel's most exact coaction, I further preferably modify said holding device by forming the spanner in the manner of a vise. One way of 85 doing this is illustrated in Figs. 15 and 16, where said spanner has one relatively fixed jaw x⁴ and one relatively movable jaw part x⁵ and said latter jaw, x⁵, being provided with a prismatic shank, is fitted to slide in guide loops x⁷ attached to the main jaw part 90 x⁴, and also to be actuated by a cam x⁸; which cam mounted fast on the spanner rock shaft x² aforesaid, can, by a partially backward rotation of said shaft, be made to work 95 against and lift the movable jaw shank x⁵ aforesaid. Upon retreat of the cam x⁸ (by a short forward throw of the rock shaft handle aforesaid) the movable jaw x⁵ and consequently also the spanner itself is released, especially if expedited by a jarring rap 100 upon the parts. But, in order that the gripping spanner thus illustrated may be vibrated into engagement with the prisms X X' on the pin shafts P²—P⁵ aforesaid, the fixed jaw part x⁴ is mounted loose upon 105 the rock shaft and both it and movable jaw x⁵ kept to place alongside of each other by being embraced between a set collar x⁹ and a pin tappet x¹¹. This pin x¹¹ fixed in, projects for some little distance alongside of 110 but without binding on said spanner's fixed jaw x⁴, and acts also as a tappet to strike 115 upon a spur x¹⁰ that fixed to projects in range from the hub or bearing part of said movable jaw x⁵. By these latter means (after the cam bearing rock shaft x² has disengaged the cam x⁸ and released the movable jaw x⁵) the tappet x¹¹ is adapted to strike 120 upon the stud x¹⁰ and when it is further thrust over to throw back the then disengaged vise-spanner from off its proper prism. This contrivance is illustrated in 125 Figs. 15 and 16; in which, in Fig. 15, the tappet and spur are in contact, and the rock shaft x² presumably acting to vibrate the gripping spanner away from the prism X; while in Fig. 16, the tappet x¹¹ is clear of the stud x¹⁰ and the cam x⁸ is thrust in so as to cause the movable jaw x⁵ to grip on 130 the embraced prism X.

As described in relation to Fig. 13, a key seat u^3 sunk lengthwise along the eye u^2 of turret U indicates means of fixing series of said turrets, each series in common alignment, on its proper pin shafts P^2-P^5 . The spanner prisms $X X'$, whose hexagonal profiles aline with those of said turret series, are fixed preferably two to each said pin shafts P^2-P^5 , and lie severally in plane of their respective spanners as above described. Said spanners, to prevent twisting of the reel, are also preferably spread wide apart and located (see Fig. 1) adjacent to the terminal sections of the reel U. The reel thus equipped presents circumferential zones of similar tool supports (U') whereon the tool sockets, u^4 , and, to at least that extent, the tools they carry, are arranged in longitudinal and equally spaced ranks. Also, as the reel U may be unlocked, and as its secondary pin shafts P^2-P^5 are in symmetrical parallelism to its main shaft P' , which latter lies in the same level or horizon as the reel U, the reel U, even by manual application affords means for bringing and holding any desired rank of said turret sockets into said mandrels' plane. However, to this end I also preferably combine with reel U what may be called its mechanical rotating device; it consists of the winch spur V' aforesaid (which, it will be remembered, when meshed with the pinion V, is operative to revolve the reel U by turning its shaft P in the bearings $p^7 p^8$; and, 2nd, and preferably in combination a turret's turning device, wherein in said winch spur gear V' , being slid endwise to disengage from the pinion V, brings its subsidiary spur gear V^2 into mesh with that one of the gears V^3 which, fixed on the adjoining end of the adjoining pin shaft P^2 or P^3 or P^4 or P^5 , is operative to rotate the series of turrets alined on and carried by such pin shaft. By these combined means any series of the turrets u' fixed to a single pin shaft may be moved mechanically until the therein selected longitudinal rank of tool sockets has been brought to line with the horizontal plane of said mandrels aforesaid and then positively and steadily locked. The flanged bottom $p^4 p^5$ of the tool holding housings $p p'$ are formed, see Fig. 4, as guide parts, fitted slidingly upon inverted V guideways $a^6 a^7$ formed on the bed A. These ways lie at right angles to the mandrel ways aforesaid. Along these ways $a^6 a^7$ the screws T T' aforesaid are operative either (1) to locate and (2) within the limits of their incidental lost motion, to hold as a locking device, or (3) reciprocally to move the entire above described puppet. For these purposes said screws T T' engage as aforesaid with the nuts $t^3 t^4$ secured to the front (angle iron) cross-piece p^3 of the puppet chair (see Figs. 1, 2, 3 and 4) are also endwise collared to M; and, connected

by gears $r^2 r^3$, act in unison as "lead" screws for the puppet component.

To keep the puppet chair with its equipment down upon the ways $a^6 a^7$ their weight may suffice, but I prefer, as in the case of the above described mandrel's carriage, positively to hold it down; here by L-shaped (removably) bolted clips, as $a^{32} a^{33}$, Fig. 4; wherein said clips will be seen to engage their L's upon and, presumably, with freedom for endwise sliding along, the faced tops of said flanged parts of the puppet housing bottoms.

Transverse to carriage ways $a^4 a^5$ and parallel to line of motion of puppet P, frame A⁴ has, see Figs. 1 and 5, formed as a shelf, a guide Z. This guide is preferably of the "hollow" dove-tail variety and embraces for endwise sliding a male part Z⁸, formed correspondingly, for that purpose on bottom of a slide block Z'. When puppet P sits, say mid way, on its ways $a^6 a^7$, said slide is long enough to extend out past the leading edge of puppet end plate p' ; to which plate it also lies near. In this position I removably connect said slide block and puppet end plate by pivoting at a^{11} (to a gudgeon a^{10} formed integral on puppet end of slide block Z') a gab link a^{12} . This link when in horizontal position, as shown in Figs. 1 and 3, can engage its gab snugly upon a pin a^{14} fixed to and projecting square from said housing p' . Thus linked slide block Z' has to follow in movement, stops, etc., puppet P. And while gab link a^{12} may be thrown in or out of engagement with pin a^{14} at any time by hand, yet to throw it out of engagement at any desired point I further preferably provide a pillar A⁹ securable (see bolt a^{15} Figs. 1, 3 and 4) where wanted on bed A, but yet so as to present (Figs. 1 and 3) in the path of said horizontally posed gab link a^{12} a tappet a^{24} . To interact with this tappet, which fixed to projects laterally from pillar A⁹ I also form the gab link a^{12} with a cam part z^3 ; and, when puppet P, in moving back from mandrel's carriage M, brings said cam z^3 into collision with tappet a^{24} , the action of said cam is, by lifting gab link a^{12} off of pin a^{14} , automatically to disconnect puppet P and slide block Z'. Moreover, whenever the split nut S¹¹ is disengaged from screw S¹⁰ (formed on shaft S⁵) the motions so producible from puppet P in slide block Z' can, if desired, be taken off and imparted to carriage M as follows:—On top of slide Z' there is clampable, in such angular adjustments as are within the limits of its engagements, a pivoting guide shoe Z². Through slots $z^4 z^5$ (formed as arcs of a circle described from the pivoting axis of said shoe) there pass freely the shanks of headed binding screws, $z^6 z^7$; of which screws the threaded tips, screwing into slide block Z', serve either to bind, or

slackened to free, said heads from the flanges about said slots and so to bind or release for angular adjustments, on Z' , said shoe Z^2 . Also in a preferably "hollow" dove-tail 5 guide way z^{18} of shoe Z' (Fig. 5) there is jointed to slide another block Z^3 . This block, by a pin z^9 (Figs. 1 and 5) engages with a throw bar z^{10} ; and said bar, passing with freedom for endwise movements through an otherwise snug fitting guide aperture m^{10} (formed in the end wall m^6 of carriage M see Fig. 5) thence extends within said carriage; and lying close to inside of side m^4 thereof, terminates under the first 10 two mandrels N N' . A little short of this inner end of throw bar z^{10} and in line with the aperture m^{10} there is, see Fig. 17, in the wall m^4 of carriage M, a transverse aperture m^{11} . This latter aperture conforms to the unthreaded neck of a screw binding bolt 15 z^{11} , and while bolt z^{11} is, longitudinally slidably therein, it is prevented from rotation by the later described engagement etc., of its L-shaped head z^{18} . A nut z^{12} , engaging upon the threaded nose of bolt z^{11} , may, 20 be screwed down on it and drawn by abutting against adjacent parts of the outer face carriage wall m . This nut z^{12} is within easy reach of what I have called, as in fact it is, 25 the operating and entrant angle of machine when viewed in plan see Y Fig. 1. Within wall m^4 said L-shaped head of bolt z^{11} embraces and in the manner of a guide (for longitudinal sliding) supports rod z^{10} , see 30 Fig. 18, or else acts to bind it to carriage M. That is to say, bolt z^{11} serves two duties, viz: 35 (1) when nut z^{12} is relaxed as a guideway and support to the otherwise free end of rod z^{10} (2) as a part by which said nut when 40 screwed home on side m^4 may bind bar z^{10} to wall m^4 and cause the carriage M to receive any endwise throw or throws which 45 said bar, by its other connections, may be in receipt. Among which connections shoe Z^2 acts, when slid in either direction in the 50 manner of an incline plane to transverse slide block Z^3 . Thus whenever puppet P and carriage M are connected by screwing up nut z^{12} , Fig. 17, and throwing in link z^2 , Fig. 3, it is obvious, should puppet P be 55 moved in either direction along its ways a^6 a^7 (by actions of the live stock aforesaid transmitted through screws T T'), then, according to the angle at which shoe Z^2 is 60 bound (by set screws z^6 z^7) on, and to the line of motion of, slide Z' , there will be developed in carriage M a very precise movement corresponding to throw of bar z^{10} . Now such movements in relation of puppet 65 P and carriage M are, when the machine—provided with work and tools—is acting, productive of taper turning. And such sort of turning—as in all other instances of the machine's action will take place in uniform synchronized progress. Also upon as many

of its mandrels N to N^5 as may be supplied with similar pieces of work and subjected to a corresponding set of tools held in the tool supports or turrets U' ; for each said turrets, of those in action, is then presenting a 70 similar tool, at any given moment and in a uniform rank and posture.

Taper turning can also be done by my lathe as described prior to, and without the aid of, the last mentioned ancillary taper turning device. For as the mandrels of the carriage M have a common controllable traverse motion across the planes of their corresponding tool socket zone (whether of the turrets (U') or of puppet P); and, as 75 said puppet carried tool sockets may be moved controllably in unison to and fro of their proper mandrels, it is obvious that relatively to each other said mandrels and tool sockets have, in the horizontal plane in 80 which they all lie, a "universal motion." By reason of this universal motion, and independent of the aforesaid slide element Z' , etc., the lathe also, as will be understood by engineers, can form substantially any taper 85 between "face-plate" and "right-cylinder" work.

To produce say, upon a face plate a volute or spiral, and referring chiefly to Figs. 1 and 6, the shaft S^2 in addition to the gearing of chair C (which chair, under control of throw rod e , may disconnect as well as rotatably engage said shaft with the main drive shaft S') also has fixed on it the gear d^8 . This gear, as above stated under control of apron E and its gears, may be operatively connected for driving in either direction with the gear E' . And gear E' by the gears e^7 E^2 and sleeve E^3 is, as above mentioned, operative to drive gear E^4 . So 95 driven E^4 drives gear e^8 , and the latter, by shaft s^5 , the gear e^9 (the back-gears), and e^9 drives pinion K, and K, the shaft S^4 . The shaft S^4 so driven, by means of lever h and its above described equipment, drives 100 any selected gear, as h^{13} , in the series h^5 to h^{18} fixed on the shaft S^3 (see Fig. 8). And this shaft, so the developer of ratable 105 rotations suitable for screw or helix motions, being thus in positive synchronized connection with the mandrel's driver, shaft S^2 , transmits such motion by gears h^{14} h^{15} to the trains of gears ($l^1 l^2 l^3$) of chair C^2 ; and such chair's trains, under control of its 110 rod c^2 , to gear F; which gear splined to, in turn, actuates with such motion the shaft s^{30} . From the shaft s^{30} (1) the clutch L is operative to impart such motion either 115 forward (by gears $l^4 l^2 s^{19}$) or backward (by gears $l^5 s^{18}$) to the shaft S^5 ; or (2) to 120 throw said shaft out of gear therewith. Now by the first of these controls and with the shaft S^2 so placed in positive connection with and operatively driving in modifiable 125 (gears $h^5 h^{18}$) synchronized relation the 130

shaft S^5 , the said two shafts become available as parts whence synchronized drive motions can be simultaneously imparted to (1) the mandrels $N-N^5$ and (2) to the carriage M . For this first of these purposes, the (1) last above, the shaft S^2 is, by reason of its endlong sliding in the bearing brackets M' of carriage M , the slots a^1 , feathers o^8 , gears o^5 o^4 , shafts o^3 and gears o^2 o operatively connected for rotatively driving in either direction the mandrels N to N^5 . Such rotations of the mandrels N to N^5 being imparted by above position connections are obviously in synchronized accord with the screw cutting or helix motions that, by the concurrent engagement of the half nut S^{11} with the screw S^{10} formed on the mid body of the shaft S^5 are at the same time communicable to the mandrel's carriage M . These synchronized movements of the mandrels N to N^5 and of the carriage M , which carries said mandrels, being invoked (by control of lever D , throw rod c , apron E and half nut S^{11}) the carriage M , it will be seen will be ratably traversed across the puppet P , which puppet, say, by dropping apron Q , so as to unmesh gears q^{10} q^8 , and also by manipulation of lever B (unclutching gears b' b^2), has for the time being its actuating shaft S^7 cut out and so left at rest is presumably presenting suitable tools in registering series to and in the range of said synchronized rotating mandrels, and thereby the machine develops coacting motions which as its several series of tools cut generate volutes in such work as said mandrels may then be charged with. "Feed" motions, or, to coin a word, "workwise" advance and retreat motions of the presenting, puppet carried, tools can be effected (1) by throwing into clutch, with lever B , the clutch b and through shaft S^7 mechanically actuating as desired the puppet lead screws T T' ; or else, (2) by said clutch being still left cut out and with apron Q^8 still dropped, by laying hold of gear q^{17} (Fig. 10) as a hand-wheel thereby, by hand, rotating shaft S^7 and so by gears r' r^3 and r r^2 turning the lead screws T T' which, acting on the nuts t^3 t^4 , Fig. 4, serve, according to their screw right or left threading, and the direction of said turning of q^{17} to advance or retreat the puppet P along its ways a^6 a^5 and so "to feed" or retreat its work presenting series of turning tools; which, if done contemporaneously with the controls manipulated for volutes as above described, will cause fusee-like forms to be generated in the work.

For screw cutting the shafts S^2 and S^5 are to be connected and driven from shaft S' in the same way as above described for volute turning, save only, that instead of using lever L to engage gears b^4 or b^5 to shaft s^{30} , said shaft is by said lever's localizing

clutch L in its intermediate position cut out and freed from said gears; then by lever B clutch b is thrown in to engage either gear b' or gear b^2 and thereby through either gear B' or gears b^8 b^9 connect said shaft s^{30} with shaft S^7 and so as to cause the latter to receive the drive coming to shaft s^{30} by way of gears k^{15} or k^{14} from shaft S' . Shaft S' , thus in receipt of synchronized rotations modifiable within the range of the gears k^5 to k^{13} is by the gears r' r^2 fixed to itself and gears r^2 r^3 fixed as heads upon the puppet lead screws T T' operative rotatively to drive them concurrently and equally either forward or back and so, by nuts t^3 t^2 cause the puppet P to advance to or retreat from the synchronously rotating mandrels $N-N^5$ with screw cutting motion. In such cylindrical screw cutting—the screws I are to be set and by banking prevent the mandrels $N-N^5$ from yielding. It is also here to be noted that as to feed motions (in and out movement of puppet P along its ways) whether of ordinary turning or screw cutting in addition to above mentioned control of the apron Q^8 (on relaxing nut q^{12} and working it with handle q^{15}) which serves to connect or disconnect at will, the shafts S^5 and S^7 ; it is also a function of the described parts—as is best seen in Figs. 9 and 10—to cause the shafts S^5 and S^7 to make, when connected for turning in one way, turn for turn, but when connected for turning in reverse, to run at different speeds. That is to say, gearing Q to Q' , Q' to Q^2 , and thence through gears q^8 and q^9 to q^{10} and by shaft q^{11} to gear q^{16} is a "2 to 1 speeding up train," but as the gear q^{16} is one half less in teeth than is the gear q^{17} there is a corresponding 1 to 2 reduction in speed and therefore shaft S^7 so connected and driven from shaft S^5 makes turn for turn therewith. But if gear Q is—by dropping apron Q^3 —connected to gear q^8 by medium of gear Q^2 , as said latter gear is smaller in diameter and less in teeth than is gear Q' there will be not only the above described relative reverse but a change to a slower speed in shaft S^7 .

Inspection of Fig. 5 will show how motions impartable through gear q^{17} to shaft S^7 are by said shaft transmissible to the puppet lead screws T T' . Otherwise with apron Q^8 dropped and shaft S^5 cut out, said Fig. 5 also shows how—especially for ordinary turning as distinguished from cylindric screw or face plate volute etc., cutting—shaft S^7 may be driven through gears B' or b^9 , and this, either slowly forward for the cutting (viz: shaft s^{30} , clutch b , gear b^2 , b^8 , and gear b^9) or quicker backward (viz: by shaft s^{30} , clutch b and gears b' and B) for retreat; also according to the intermediate disengaged portion of clutch b , as shown in Fig. 8, and determined by manipu-

lation of lever B, the said shaft S⁷ and the parts it actuates left at rest.

Having given above by way of samples of certain general coactions of the live stock 5 mandrels and puppet components, I now pass to consideration of the remaining chief element of the preferred complete invention, viz: Preferably when the tool holders or turrets U' are not engaged holding tools to 10 work—and, in the illustrative case, for those diametrically opposite to the mandrels N—N⁵—I have also provided that the tools they hold may be sharpened, each sort in symmetrical conformity, and all without removal 15 from their holders or turrets. This is illustrated in Figs. 1, 2 and 3, by an ancillary but preferably combined and coacting tool grinding element, for which element A¹⁰ is a tabular dove-tail guide. This guide part 20 alleys axle P' of puppet P, also the guide ways a⁴ a⁵ of the mandrel's component, but extends transverse to, back of, and substantially across the puppet ways a⁶ a⁷. It is conveniently formed as an integral table, 25 say cast with the bed A, and has fixed along the center line of top, a rack W. By registering hollow dove-tail embracing parts there is mounted on guide A¹⁰, with freedom for sliding end-long thereof, see Figs. 2 and 30 3, a slide rest. This rest, while it may be of various sorts is, in this illustrative case, of the compound dove-tail interguiding character familiar, so far as its detail, construction, and motions are concerned as the tool 35 support of say an ordinary engine lathe, I therefore, shall herein only identify its chief members, and omit, as unnecessary to describe, the more minute details as well as many of the movements of which it is capable. And this I do, as follows:—W' is the saddle of said slide rest, which saddle embracing for sliding along the dove tail part 40 of is guided by the aforesaid guide A¹⁰. W² is the swiveling traverse guide block of said 45 slide rest; which block, having a male dove-tail guide upon its top face, thereby engages with a registering "hollow" dovetail foot, w¹⁰, of a grinder head W³, which grinder head is thereby slidingly attached thereto. 50 w⁴ is the pivot bolt about which, when slackened, traverse block w² can be slewed, or by which when set up with or without the interposition of (elevation controlling) packing washers w⁶, the said block and saddle 55 can be clamped in horizontal angular adjustment. For facility of traveling this slide rest along the rack W I also journal in and to said rest a shaft w⁶: which shaft, where it crosses said rack W, has fixed to it a small 60 pinion w⁷ whose teeth register and engage with those of said rack; and also, upon one end of said shaft, which end, for this purpose, projects in the clear I fix a crank handle w⁸. To hold said rest at any desired 65 point or points along A¹⁰ I provide a lock-

ing device or devices—as the set screws w⁵⁰ and w⁵; of which screw w⁵, threaded through the foot of said rest, can, when set up, bear its preferably flat point upon the guide A¹⁰ and so lock the slide rest at any place along it. But as it is also often convenient to lock the rest at definitely spaced points along the guide A¹⁰, I also, in Fig. 1, have indicated by a series of graduated or equally spaced circles a²⁰, certain conical pits—wherein the 70 nose of a registering cone frustum point of the other set screw, w⁵⁰, (also threaded through the foot of said slide rest) may be set when required, and so localize with precision, and hold in such predetermined spacing the said slide rest. The grinder head above referred to being, so far as its foot, w¹⁰ aforesaid is concerned, a part (viz: cross slide) of said slide rest, is also, so far as it is a grinder, mechanism familiar and needs here 75 the combinational characteristics set forth rather than detail description of its own proper parts, therefore, of it as follows, only:—Inspection of Figs. 1, 2 and 3, will, show the housing of said head W³ to be of 80 the usual pedestal foot and forked top, shaft bearing, type: in the forked top bearings W² thereof there is journaled the shaft w'; which shaft has fixed upon it (1), between the forks, a belt wheel w⁹, and (2), upon its 85 longer projecting end, a disk shaped grinding wheel w². The whole presumably beltable to, and, as desired actuatable from a suitable source of power—such as a drum pulley, in length co-extensive with guide 90 A¹⁰, and a controllable countershaft; but when referred to all this also comes to things familiar and need not herein further be described nor illustrated save by the belt wheel w⁹ aforesaid. 95

While the height of the grinder wheel w² above bed A is variable, according to the number or thickness of aforesaid packing washers w⁶, the height illustrated in Figs. 2 3, which height conforms the axes of the 100 grinder, puppet shaft P' and mandrels N to N⁵ to a common plane, is substantially that which, in this illustrative case, best lends itself to the grinding of tools ordinarily in use in turret lathes. 105

In reference to the mode of operation, inspection of Figs. 2 and 3 will make obvious that, if the three following things be done, viz: (1) Reel U released (by throwing with handle spanners x x' clear of prisms X X'). 110 (2) Said reel rotated one half turn (180°) from position shown in Fig. 2, and, (3) the pin shaft P² left unrotated, that the tools T¹⁰ which (with or without tool holders, as T¹¹) had been seated in the sockets w⁴ and 115 presented right side up in range of said mandrels, then would be in reverse—or upside down and directed backward toward the grinder element. This backward direction and upside down position of such tools 120

125 130 135 140 145 150

is shown in Fig. 3 by a tool T^{10} on grinder side of pin shaft P^4 . Obviously also by a suitable rotary movement or movements of reel U —indicated by the curved arrow located between P^5 and P^4 in Fig. 2—any of the other tool holding turrets U' may be brought to the grinder side of said puppet. Being there, since the turrets U' are also normally rotatable with and by their proper pin shafts P^2 — P^5 , any tool, as T^{10} , in turret U' of pin shaft P^4 Fig. 2, by a suitable rotation of its supporting pin shaft, is presentable to the range of the grinding wheel w^2 . This is diagrammatically illustrated in Fig. 2 by the curved arrow which, centered on axis of shaft P^4 , extends from said tool to the broken line connecting axis of grinder shaft w^6 and that of said pin shaft P^4 .

For generating with the range of the grinder wheel w^2 along and about the guide A^{10} and upon the working ends of the tools T^{10} , say, substantially any of the usual turning tools, edges, I have made the following provision:—Chiefly an accurate and mechanically controlled universal motion due to (1) the right angle relation of the guides, A^{10} , of the grinder and $a^6 a^7$ of the puppet aforesaid; (2) the movability of the grinder slide rest (W^2) and the puppet P along said guides; and (3) the motions for moving said rest and puppet thereon; of which motions, apart from the said rest's own proper ones, the above described rack and pinion, $W w^7$, and the aforesaid highly controllable puppet lead screws $T T'$ are the chief components. Under the control of these motions—especially when coupled and combined with such other slidings, pivoting, changes of elevation, localizations, etc., as are available by reason of the above mentioned ordinary constructive arrangements of said slide rest and grinder a great variety of movements appropriate to grinding turning tools may be developed and therefore such non-active tools in reverse, as aforesaid, ground by the presumably belted, driven, and coacting grinder wheel w^2 .

By way of examples: (1) to produce a hollow ground relief on the nose of a flat finishing tool such as is shown at t^{10} on tool T^{10} (right side) of turret U' , Fig. 13, and prior to the interpassage of said tool and grinding wheel w^2 , a downward tilt to an angle equal to that of the desired relief may be given to the reel U . Such tilting of reel U , prior to interpassage with, and for the production of a relief angle tool is diagrammatically illustrated in Fig. 2 by (1) a vertical dot and dash line passed tangent to and upon puppet side of, the circumference of grinding wheel w^2 , and (2) by a second dot and dash line connecting a point, a little below center of said grinding wheel, on aforesaid vertical line and the axis of reel

U. Otherwise, reel U being held fixed—as by throwing spanners $\alpha \alpha'$ into grip with prisms $X X'$ —a similar tilt, for a similar purpose, may be given to the, at the time, grinder presenting pin shaft: as P^4 , Fig. 2, which act as the turrets are fixed to it, equally and simultaneously tilts them all. This alternative mode of tilting for relief is also diagrammatically illustrated in Fig. 2 by the double dot and dash line connecting axis of pin shaft P^4 and the vertical dot and dash line passed, as above mentioned, tangent to grinding wheel w^2 .

To produce relief on a lateral facet, as the facet t^{15} on tool T^{10} , prior to the grinding act such tool itself may be tilted from its normal setting in its proper socket u^4 to such angle as conforms to that of the desired relief. This "tool tilting for relief" is provided for in the illustrative case by the uniform circular cross-section of the tool shanks (also those of the tool holders), which shanks fit snugly, but when the binder bolts u^7 are slackened with capacity for rotation in their registering cylindriform socket u^4 . Such tool tilting for lateral relief is diagrammatically illustrated in Fig. 14 by a vertical central secant dash line indicating the normal cutting position of such tool and two dot and dash lines radiating from said center and on either hand of said vertical line at approximately three degrees (3°) each. Their said divergence indicating appropriate right and left hand tiltings for the relief facets of iron turning "right" and "left" side tools. Having so acted and ground any one tool presented in the then nearest socket u^4 of one turret U' it is obvious that a one quarter rotation of the reel U will (the pin shafts P^2 — P^5 left or held, at rest) bring the outermost socket u^4 of another similarly alined turret with the tool it may hold into corresponding position and so on by suitable rotation of reel U , or of the turrets U' any or all the tools of any given zone, if need be can be brought similarly and in precisely the same relation to the grinder and be, by it, ground in conformity to the tool first ground. This I call grinding by zones, whether it be in the great zones of reel U , or in the lesser ones of the individual turrets U' . Or having ground, say the relief face of one turret held and reel supported tool—say facet t^{16} of the upside down tool T^{10} in the grinder adjoining facet and turret U' of Fig. 3—it is obvious that by manipulating the winch crank w^8 the grinder W^3 may be moved along the tabular guide A^{10} brought to bear and to act in exact alined conformity upon say an exactly similar facet of a similar and similarly postured tool seated in the corresponding socket u^4 of the next adjoining turret; in this instance the grinder adjoining facet u^4 , which in Fig. 1 is alined (in transverse di-

rection to the slide rests travel on guide A¹⁰) with the mandrel N⁴. Then by the action of grinding wheel w² and an interpassage of said wheel and said second tool similar to that had for the first tool, said second and flanking tools corresponding facet will be ground like in form and position to that of the first tool and so for other facets. Thus in both the shape of their cutting edges—
10 which edges, speaking generally, are the product of the intersection of two such facets on a single tool, though it may be of but one or possibly of more than two,—I contrive that two tools may be ground both alike and
15 to like alinement with the respective co-operating mechanisms whether of puppet or mandrel's component, as aforesaid. And so, one after another, all similar tools in any one rank of the turrets U' may be brought to
20 range of the grinder and then ground to precise alined conformity; and when one rank is so ground, any other desired rank or ranks may be brought by the movements of the puppet P and reel U to the grinder side
25 and ground.

In rotating the pin shafts P² P⁵ for any purpose the pinions V³ fixed to their ends adjoining the operating angle Y, Fig. 1, afford convenient "hand wheels." So, too,
30 the toothed peripheries of these wheels V³—especially if their toothing be a multiple and alined with the number of the equally spaced, radiate turret sockets u⁴—afford dials convenient for gaging the tilt angle of
35 the turrets in grinding for relief as aforesaid. The pinion V can also be used in the same manner as a tooth dial for tilts of reel U, though, of course, it is more easily worked by the winch handle n'.

40 To hold the turrets U' at any tilt, however established, each pin shaft P²—P⁵ may be equipped as shown in Fig. 1 with a set screw y, which screws engaging their threaded part in tapped ends of reel arms u can, when set up, bear on and bind their proper shafts from rotation. It would be tedious, as well as unnecessary to give further uses or modifications of the grinder element, the novelty whereof resides rather in the fact of
45 its combination as a highly organized, in itself well understood, and capacious tool sharpener—with the other elements of my invention, than in its own novel features; yet before passing from the grinder element, so interguided and combined with the other features of my invention, there remains to be stated a matter which while it is, at times, distinctly separable from the above described and, as I shall call it,
50 "grinding in site," function is also at times a matter which, as I contrive it, not only leads to but often merges with said prime function of the grinder. Therefore, also as follows: A previously and independently
55 ground tool, if correctly set in any of the

tool sockets u⁴ of aforesaid turret lathe may be proved to be so set by going over its facets with grinding wheel w² in the manner of a surface gage. To which end the motions of said slide rest and grinder head are, of course, admirably adapted. If any ready ground tool so seated can be gone over by the wheel w² in its surface gaging capacity without grinding or clearance and from a definite locus, or say with screw w⁵⁰ set into one of the pits a²⁰, it is proof, not only that said tool is correctly ground, but also that it is in correct position. But, if such tool protrude at any part, the grinder wheel w² being actuated, it, at the instant of detection, will proceed to reduce said tool to and by the proper amount. Or, lastly, should said wheel w² fail, either to contact or grind, the operator has notice of a "clearance." Such clearance he can provide for by correctly resetting such defectively set tool, and then proceeding to the incidental grinding down of any part or parts thereof which such resetting caused to protrude in excess of the path traversed by said tool and the, in this instance, combined surface gaging and tool grinding element. In combination with or without a grinder element it is, however, not only possible, but well within the purview of my invention, that a ready ground finished tool or tools may be attached alone or together with, and so alined in rank and zone or zones with, those of its sort, in their proper rank or ranks and zone or zones, of turret or reel in the hereinbefore illustratively described multiple reproduction lathe, that the said ready ground tool or tools shall conform to its proper place therein with precision, and therefore act in uniformity with its mates. This is especially applicable for the tools which first meet with or "rough" the work; yet as charging the machine with ready ground tools, especially of the intermediate (small duty) and finishing sorts, is likely to be slow of attainment, or at the cost of much gaging and measuring, it is not so desirable nor, in practice apt to be productive of so uniform work as the full preferred combinational set forth above.

The multiplicity of tools which a multiplicity of turrets, each capable of holding and in quick succession, presenting a number of tools to its proper piece of work lends itself to putting but a minimum duty on each tool and especially least of all upon the finishing tools which, acting last upon previously highly machined surfaces, will have almost ideal conditions to meet in their performance. This feature of my invention leads to the long life and infrequent grinding of said finishing tools, as well as to their almost absolute accuracy in uniform performance.

The whole machine, as hereinbefore illus

tratively described being organized with reference to control by a single turner (whose station will generally be at the corner Y Fig. 1) affords striking economy in wages; 5 for speaking in terms of the ordinary turret lathe, and without the addition of the novel four to one turrets to mandrel arrangement of the illustrative case, this my lathe is to the ordinary turret lathe as the 10 multiple mandrels thereof are to the ordinary turret lathe's single turret; or in this illustrative case, as 6 to 1, capacity for expansion is diagrammatically illustrated in the interruption of the plan view Fig. 1. 15 All parts wholly omitted in said interruption are obviously fully illustrated in the parts shown on either hand thereof and obviously could be expanded or contracted in numbers. Of course much more could be 20 specified both of the turning and grinding detail and actions but with the above as salient samples, and as the several modes of operation of its chief components, as well as those of the subsidiary, interacting parts, 25 have already been given incident to the foregoing description of the illustrative and the preferred form of my invention, it remains, only, to add of the whole that: The lathe as above described even when using only 30 one mandrel with only one of its corresponding puppet carried turrets U'— the other parts being cut-out or left running idle— can produce practically every species of work within range of an up to date Ameri- 35 can turret lathe. Also that the lathe above described when using the least plurality of its mandrels, say N and N⁵, each of them with one only of their corresponding puppet carried turrets, acting with one or more 40 similar similarly postured and successively occurring tools upon a corresponding number of similar pieces of work (engaged and carried by said active mandrels) is then operative to turn said pieces of work in 45 duplicate. And so the lathe is operative, whatever the number, from two to the full number of its plural mandrels, to produce, in multiple, reproductions. Also that the lathe, as above described, can bring to bear, 50 (especially when the tool supporting parts thereof are in multiple and actioned as the turrets U' aforesaid are) such a numerous succession of tools that the most complex, as well as accurate results may be effected. 55 And each piece of work is by my said lathe simultaneously and similarly treated by a large number of tools brought successively, quickly and accurately to a prescribed alinement, and there, while operating, conveniently and positively controlled by the described mechanisms under the manipulation of, if need be, a single operator. All this 60 lends itself to rapidity of output; to a minimizing of wear; also to infrequent sharpening and a consequent long life and accurate

action of the individual tools employed in its embodiments.

Divested of the grinding element a lathe thus organized will give a tolerable uniformity between all the units of work in any 70 one batch of its output, that is to say, fairly well standardized work may be produced in it by careful tool setting only. But when precision of high degree is demanded, not merely careful tool setting and those novel 75 and comprehensive adjustments of which my novel combined turrets and their related mandrels are severally susceptible may be called upon to arrive at it, but the same is further provided for and in reality assured 80 by the machines preferred and full construction, which gives capacity for grinding the cutting edges, especially those which in any given turret rank act, last, in site. Obviously, as hereinbefore indicated, it does 85 this grinding by a coactive, and, in relation to each mandrel and its correlated turret section, a definitely locative grinding element. This grinding of like turret held tools rank after rank, by an element whose 90 location is first selected empirically as the one best meeting either the true or accidentally inaccurate relations (alimentments) of the respective turret mandrel sections, is im- 95 portant and temporarily established in the 95 illustrative case by binding the flat nosed set screw w⁵, to guide A¹⁰, and finally given a definite relocative "point" thereon by forcing into the pits a²⁰ with the sharp pointed nose of its mate the set screw and 100 grinder locator w⁵⁰. Such coactive grinding from definite locative points each found by cut and try methods and then unalterably established is a marked and novel character- 105 istic of my lathe; in fact incorporates in it the grinder and causes the tools so ground and found in position produce in and by each turret mandrel section work of exact conformity to that of any or all its mates.

Having now described my invention, what 110 I claim as new and desire to secure by Letters Patent is,

1. In a lathe, a live stock, a mandrels' component, having a plurality of mandrels journaled therein, and a puppet having portions cooperatively related to each of said mandrels, said live stock, mandrels' component and puppet being mounted each in its own housing, a common bed supporting all of said housings, connections between said 115 live stock and each of said mandrels for rotating the latter, and connections between the live stock and said mandrels' component, whereby said live stock positively moves said mandrels' component bodily relatively 120 to said puppet, and means for operating the puppet.

2. In a lathe the combination of an actuating live stock, a movable mandrels' carriage, a plurality of mandrels, mechanism 125

comprising shaft S^2 , bevel gears o^4 , o^5 , the latter splined to said shaft S^2 , but journaled on and carried by mandrels' carriage, transverse shaft o^3 , pinion gear o^2 , and mandrel gear o whereby each said mandrels are positively connected to and revolute in unison from said live stock, a puppet having a guide part or parts, a guide or guide parts therefor, a plurality of turrets pivotally connected to said puppet and adapted to register and coact with said mandrels substantially as described.

3. In a lathe the combination of a live stock mechanism, a plurality of mandrels operatively connected thereto and in receipt of synchronized motions therefrom, a movable puppet housing having a guide part or parts, a guide or guides therefor, a reel pivotally connected to said movable puppet housing and a plurality of turrets pivotally connected to said reel and adapted by their tactical arrangement and said pivotal connections to coact in series with said mandrels, substantially as described.

25 4. The combination with a live stock of a puppet provided with a plurality of tool supports, a movable mandrel carriage and a plurality of mandrels mounted therein, screws and engaging nuts for adjusting the 30 tool supports relatively to each other to bring them in registering conformity with the several mandrels, driving connections between the live stock and the mandrels, whereby the latter are rotated by the former, and connections between the live stock and the mandrel carriage whereby the carriage is positively moved by the live stock relatively to said puppet with a speed definitely proportionate to that of the turning 35 movements of the mandrels.

5. In a lathe, the combination with a movable puppet and a movable mandrels' component, of a self contained relatively fixed live stock comprising a mandrels' motion shaft S^2 , a puppet motion shaft S^7 , a main driver, mechanism operatively connecting said main driver and said puppet and mandrels' motion shaft, and mechanism for transmitting motion from said shafts to said 45 puppet and mandrels' component to positively move each bodily relatively to the other and the live stock.

6. In a lathe, the combination with self contained guided and relatively movable 55 puppet and mandrels' components, said mandrels' component, having one or more mandrels in cooperative relation with said puppet, of a self contained relatively fixed live stock, said live stock comprising a shaft 60 for rotating said mandrels, a shaft for positively and bodily moving said mandrels' component relatively to said live stock and puppet, a main driver mechanism, a puppet motion driver mechanism for bodily moving 65 said puppet, mechanisms of control and

transmission operative to connect and disconnect said shaft and said main driver mechanism, and mechanism of control and transmission operative to connect and disconnect said puppet motion driver mechanism and said puppet.

7. The combination of a relatively fixed live stock having a mandrels' shaft S^2 , a screw cutting motion shaft S^5 , and a puppet motion shaft S^7 , of a mandrels' carriage 75 transversely movable, mandrel or mandrels operatively journaled therein, a tool holder or holders, a movable support therefor, a guide mechanism operative to keep said tool holder support to a line in the normal prolongation of the axis or axes of said mandrel or mandrels, a lead screw or screws (T T') operatively engaged with said support, mechanism operatively connecting said puppet motion shaft (S^7) and said lead 80 screw or screws of said support, and mechanisms whereby not only said mandrel or mandrels and said mandrels' motion shaft may be operatively connected, but whereby also said mandrels' motion shaft may be operatively 85 connected synchronously to impart drive motion to said screw cutting shaft (S^5) substantially as described.

8. The combination of a live stock having a mandrels' motion shaft S^2 , a screw cutting 95 motion shaft S^5 , and a puppet motion shaft S^7 of a mandrels' carriage, a mandrel or mandrels operatively journaled therein, a tool holder or holders, a movable support therefor, a guide mechanism operative to 100 keep said tool holder support to a line in the general prolongation of the axis or axes of said mandrel or mandrels, a lead screw or screws (T T') operatively engaged with said support, mechanism operatively connecting 105 said puppet motion shaft S^7 and said lead screw or screws of said support, vibrative apron Q^8 and gears Q , Q' , Q^2 , alternative drivers of gear q^8 operative to connect with reversing motion screw cutting shaft S^5 with 110 said puppet motion shafts S^7 also mechanism operative to connect or disconnect, comprising vibrative apron Q^8 , and gears q^1 and q^2 , said screw cutting and puppet motion shafts and mechanism whereby not only 115 said mandrel or mandrels and said mandrels' motion shaft may be operatively connected, but whereby also said mandrels' motion shaft may be operatively connected synchronously to impart drive motion to said screw cutting shaft S^5 substantially as described.

9. The combination of a live stock having a mandrels' motion shaft S^2 , a screw cutting motion shaft S^5 and a puppet motion shaft S^7 , of a mandrels' carriage, a mandrel or mandrels operatively journaled therein, a tool holder or holders, a movable support therefor, a guide mechanism operative to 125 keep said tool holder support to a line in the 130

- general prolongation of the axis or axes of said mandrel or mandrels, a lead screw or screws (T T') operatively engaged with said support, mechanism operatively connecting said puppet motion shaft S^7 and said lead screw or screws of said support, vibrative apron Q^3 and gears Q, Q', Q^2 and gears $q^8, q^5, q^{10}, q^{16}, q^{17}$, journaled in part on studs q, q', q_{13}, q_{11} , operative to connect with reversing motion, the said screw cutting and puppet motion shafts S^5, S^7 , respectively and mechanisms whereby not only said mandrel or mandrels and said mandrels' motion shaft may be operatively connected, but whereby also said mandrels' motion shaft may be operatively connected synchronously to impart drive motion to said screw cutting shaft S^5 substantially as described. 10
10. The combination of a live stock having a mandrels' motion shaft S^2 , a screw cutting motion shaft S^5 , and a puppet motion shaft S^7 of a mandrels' carriage, a mandrel or mandrels operatively journaled therein, a tool holder or holders, a movable support therefor, a guide mechanism operative to keep said tool holder to a line in the general prolongation of the axis or axes of said mandrel or mandrels, a lead screw or screws (T T') operatively engaged with said support, mechanism operatively connecting said puppet motion shaft S^7 and said lead screw or screws of said support, mechanism operative to connect or disconnect said screw cutting and puppet motion shafts, and mechanism whereby not only said mandrel or mandrels and said mandrels' motion shaft may be operatively connected, but whereby also said mandrels' motion shaft may be operatively connected synchronously to impart drive motion to said screw cutting shaft S^5 substantially as described. 20
11. In a lathe the combination with movable guided mandrels' and puppet components of a relatively fixed live stock, said live stock comprising a mandrels' motion shaft S^2 , a driver, a screw cutting motion shaft S^5 , pivoted split nut S^{11} or its equivalent mechanism for controllably connecting said screw with said mandrels' component, mechanism operative controllably to connect, disconnect, reverse and rotatably transform a portion of the drive of said mandrels' motion shaft to said screw cutting shaft, and thereby concurrently, and in synchronized relation, to develop screw cutting drive motions in said shaft S^5 , substantially as and for the purposes described. 30
12. The combination in a lathe of a live stock having a mandrels' motion shaft S^2 , a screw cutting motion shaft S^5 and a puppet motion shaft S^7 , of a movable mandrels' carriage, a mandrel or mandrels operatively journaled therein, guide mechanism operative to keep said mandrels' carriage in a definite line of movement, a screw operatively connected with said screw cutting motion shaft and also connectible to said mandrels' carriage, for traversing the said carrier along said guide mechanism, a tool holder or tool holders, a movable support therefor, a guide mechanism operative to keep said tool holder support to a line at right angles to that of the movement of said mandrels' carriage, a lead screw or screws operatively engaged with said support, and mechanisms of transmission whereby said puppet feed shaft S^7 and said tool holders' support may be operatively connected, and whereby said mandrel or mandrels and said mandrels' motion shaft may be operatively connected, the whole for producing volutes, fuses, etc., substantially as described. 40
13. The combination in a lathe of a live stock having a mandrels' motion shaft S^2 , a screw cutting motion shaft S^5 , and a puppet motion shaft S^7 , of a movable mandrels' carriage, a mandrel or mandrels operatively journaled therein, guide mechanism operative to keep said mandrels' carriage in a definite line of movement, nut S^{11} and screw S^{10} operative reciprocally to move said mandrels' carriage along said guide, a tool holder or holders, a movable support therefor, guide mechanism operative to keep said tool holder support to a line at an angle to that of the movement of said mandrels' carriage, mechanism operative reciprocally to move said tool holder support along its guide line, and mechanism of connection and transmission whereby said mandrels' motor mechanism and said screw cutting shaft S^5 may be connected and said tool, holder supports' lead screw mechanism T T' actuated so that the said puppet motion shaft S^7 and said screw cutting motion shaft S^5 of said live stock may be alternately connectible, and mechanism whereby said mandrels' motion shaft may be operatively and synchronously connected for imparting drive motions to said screw cutting shaft, substantially as described. 50
14. The combination in a lathe of a live stock having a mandrels' motion shaft S^2 , a screw cutting motion shaft S^5 , and a puppet motion shaft S^7 , of a movable mandrels' carriage, a mandrel or mandrels operatively journaled therein, guide mechanism operative to keep said mandrels' carriage in a definite line of movement, a mandrels' carriage lead screw S^{10} formed on said screw cutting motion shaft and engaging with said mandrels' carriage, a tool holder or holders, a movable support therefor, guide mechanism operative to keep said support to a line at an angle to the line of movement of said mandrels' carriage, a lead screw or screws operatively engaged with said tool holder support and mechanisms of transmission, one operatively connecting said puppet motion shaft and said tool holder 60

support, and another operatively connecting said mandrels' motion shaft and said mandrel or mandrels, whereby the said mandrels and tool holder supports may be 5 operatively driven substantially as described.

15. In a lathe the combination of a live stock, a movable mandrels' carriage, a movable puppet, a bed having shaft housing frames and mandrels carriage and puppet 10 guide parts formed thereon, said ways being located transverse to each other substantially as described.

16. The combination with a live stock having a mandrels' motion shaft S^2 , a screw cutting motion shaft S^5 , and a puppet motion shaft S^7 , of a movable mandrels' carriage M , a mandrel or mandrels operatively journaled therein, guide mechanism operative to keep said mandrels' carriage in a definite line of movement, a mandrels' carriage lead screw S^{10} , formed on said screw cutting motion shaft and engaging with said mandrels' carriage, a tool holder or holders, a movable support therefor, guide mechanism operative to keep said turret support to a line at right angles to that of the movement of said mandrels' carriage, a lead screw or screws operatively engaged 25 with said turret support and mechanisms of transmission whereby said puppet feed shaft S^7 and said turret support may be operatively connected and whereby said mandrels and said mandrels' motion shaft S^2 30 may be operatively connected substantially as described.

17. In a lathe, a mandrels' component, having a plurality of mandrels, tool holders for the several mandrels pivotally connected to a single support to turn relative thereto 40 about an axis extending transversely to the mandrels and mechanism for adjusting the tool holders relatively to each other in a direction parallel to said axis.

45. In a lathe, the combination of a mandrel, mechanism for driving said mandrel, a tool holder or tool holders pivotally connected to a support, and the screwed pin shaft P^4 and jam nuts j, j', j'', j''' , for nicely adjusting said tool holder or holders in directions transverse to the pivoting movement thereof, substantially as described.

55. In a lathe, the combination of a plurality of mandrels mechanism for driving said mandrels, a tool holder or holders for each of said mandrels, each tool holder being mounted on a pivotally supported pin shaft extending transversely to said mandrels and means for adjusting the tool holders relatively to each other, comprising threads on the pin shafts and nuts j, j', j'', j''' .

60. In a lathe, the combination of a plurality of mandrels, mechanism for simultaneously operating them, a positively movable puppet component adapted both to pre-

sent to said mandrels a corresponding series of tools and also by rotative support to expose the said tools when non-active in reverse to a grinding element, said element, a guide therefor, said guide being formed on 70 an integral part of the lathe's bed, said bed, said rotative puppet support and means for rotating to and holding the same in definite positions substantially as described.

21. In a lathe the combination with the 75 described movable puppet and mandrels' components, each movable transversely of the line of movement of the other, of a live stock mechanism operative to produce screw cutting motions, described controllable gear 80 selective train and lead screw, mechanism whereby said puppet and mandrel's components may be connected with each other for such screw cutting motions and concurrently driven from said live stock, mechanism 85 whereby interconnection between mandrels' component and puppet component may be disconnected, mechanism operative to connect said puppet component when so disconnected with an independent actuating 90 mechanism for ordinary turning and said independent puppet actuating mechanism.

22. In a lathe, the combination with a mandrel or mandrels as described, a main drive mechanism comprising a motor shaft 95 S' , a change of speed gear train consisting of gears g to g^5 , shaft s' , movable chair C and controlling rod c , a longitudinally adjustable pinion gear d adapted to mesh with any one of the drive gears g^3, g^2, g^5, g^4 , 100 of said change of speed train said gear for this purpose having a spline slotted eye, spline d' engaging therewith and also connections as described to a controlling lever D , said lever, a slotted shaft S^2 engaging 105 said spline and thereby rotatively operative as a source of variable speed motions to the mandrel or mandrels aforesaid, substantially as described.

23. In a lathe the combination with puppet and mandrels' components as described, a main drive mechanism comprising a motor shaft S' , a change of speed gear train 110 consisting of gears g to g^5 , shaft s' , movable chair C and controlling rod c , a longitudinally adjustable pinion gear d adapted to mesh with any one of the drive gears g^3, g^2, g^5, g^4 of said change of speed train, said gear for this purpose having a spline slotted eye, spline d' engaging therewith, 115 and also connections as described to a controlling lever D , said lever, a slotted shaft S^2 , engaging said spline and thereby rotatively operating as a source of variable speed motions to the mandrel or mandrels 120 aforesaid, a shaft S^6 operatively connectible to and for driving by said shaft S^2 aforesaid and mechanism operatively connecting aid drivable shaft S^5 with a puppet lead screw or screws and said lead screw or 125 said lead screw and said lead screw or 130

screws engaging with an operative to impart movement to said puppet substantially as described.

24. In a lathe the combination with puppet and mandrels' component as described of a main drive mechanism, which mechanism comprises main shaft S', means for rotatively driving the same, change of speed gears g to g⁵, chair C, controlling rod c, controlling lever D, longitudinally adjustable pinion gear d, splined shaft S², from which drive motion is taken off to the mandrels N to N⁵, reverse motion controlling apron E and its gears as described, sleeve gears E⁴, E², back gears e⁸ e⁹ and their shaft s⁵, pinion K and its shaft S⁴, said shaft having slot k²¹, traveling spline k²⁰, gear k², controlling lever k, set screw k⁵, sloping rail a, nest of thread differentiating gears k⁵ to k¹³, shaft S³ driven thereby, gears k¹⁵ k¹⁴ fixed to said shaft S³, speed transforming gears l² l³ l l', controlling rod c², movable chair C² operative to mesh one or other of said four latter gears with the longitudinally adjustable gear F, said gear so movably adjustable, its engaging spline f, correspondingly spline slotted shaft s³⁰ whereon gear F is longitudinally slid able but rotatively splined, controlling lever L', clutch L, its clutch gears l⁴, l⁵, the intermediate idler l²⁰ forming a device operative either to leave at rest or drive alternately in opposite directions the gears s¹⁸ s¹⁹, said gears fixed to shaft S⁵ and said shaft so equipped as a screw cutting motion shaft; also a puppet drive motion which consists of belt wheel s⁷, shaft s⁶, spur gear b¹⁰ fixed to said shaft s⁶ and pinion gear B' fixed to shaft S⁷, said shaft S⁷, a cut out and reversing motion mechanism consisting of clutch b splined rotatively to but slid able endlong upon said shaft s³⁰, gears b' b² provided with parts to engage said clutch when slid to them, and mounted otherwise with rotative freedom but endwise collaring on said shaft s³⁰, a lever B to control said clutch, a gear B' fixed to said shaft S⁷ and meshing with clutch gear b' aforesaid, a gear b⁹ fixed to said shaft S⁷ and meshed immediately by reverse motion gear b⁸, with clutch gear b², and said reverse motion gear b⁸, the whole operative to permit the shafts f² S⁷ and S⁵ to be driven either by way of the belt wheel s' or the belt wheel s⁷ substantially as and for the purposes described.

25. In a lathe the combination with a movable mandrels' carriage and a lead screw operative to move said carriage, of a live stock having a screw motion shaft, a driver or drivers therefor, a cut out or cut outs, comprising clutches L, b, and lever controlled gear k², operative to cut out and leave said screw motion shaft free of said driver or drivers, and a subsidiary "handy jack" driver independently operatable and positively engaged with said screw shaft substantially as described.

26. In a lathe the combination with a mandrels' motion shaft of another shaft operatively connected thereto by transmitting and rate transforming mechanism, said latter mechanism being susceptible of producing in said other shaft screw cutting motions, a clutch L operative to connect and disconnect said mandrels' motion shaft and said other shaft, a clutch b operative to connect and disconnect with said other shaft a drive mechanism proper to itself, said latter drive mechanism, and an independently operatable mechanism operative upon said other shaft as a handy jack substantially as described.

27. In a lathe the combination with a mandrels' motion shaft of another shaft operatively connected thereto by transmitting and rate transforming mechanism, said latter mechanism being susceptible of producing in said other shaft screw cutting motions, a clutch L operative to connect and disconnect said mandrels' motion shaft and said other shaft, a clutch b operative to connect and disconnect with said other shaft a drive mechanism proper to itself, said latter drive mechanism, and an independently operatable mechanism operative upon said other shaft as a handy jack substantially as described.

28. In a lathe the combination with a movable mandrels' carriage, a movable puppet, lead screws for and operative to move said carriage and puppet, a live stock having a screw motion shaft, a driver or drivers therefore, a cut-out or cut-outs operative to cut out and leave said screw motion shaft.

adjustable gear F, said gear so movably adjustable its engaging spline f, correspondingly spline slotted shaft s³⁰ whereon gear F is longitudinally slid able but rotatively splined, controlling lever L', clutch L, its clutch gears l⁴, l⁵, the intermediate idler l²⁰ forming a device operative either to leave at rest or drive alternately in opposite directions the gears s¹⁸ s¹⁹, said gears fixed to shaft S⁵ and said shaft so equipped as a screw cutting motion shaft; also a puppet drive motion which consists of belt wheel s⁷, shaft s⁶, spur gear b¹⁰ fixed to said shaft s⁶ and pinion gear B' fixed to shaft S⁷, said shaft S⁷, a cut out and reversing motion mechanism consisting of clutch b splined rotatively to but slid able endlong upon said shaft s³⁰, gears b' b² provided with parts to engage said clutch when slid to them, and mounted otherwise with rotative freedom but endwise collaring on said shaft s³⁰, a lever B to control said clutch, a gear B' fixed to said shaft S⁷ and meshing with clutch gear b' aforesaid, a gear b⁹ fixed to said shaft S⁷ and meshed immediately by reverse motion gear b⁸, with clutch gear b², and said reverse motion gear b⁸, the whole operative to permit the shafts f² S⁷ and S⁵ to be driven either by way of the belt wheel s' or the belt wheel s⁷ substantially as and for the purposes described.

29. In a lathe the combination with a movable mandrels' carriage and a lead screw operative to move said carriage, of a live stock having a screw motion shaft, a driver or drivers therefor, a cut out or cut outs, comprising clutches L, b, and lever controlled gear k², operative to cut out and leave said screw motion shaft free of said driver or drivers, and a subsidiary "handy jack" driver independently operatable and positively engaged with said screw shaft substantially as described.

30. In a lathe the combination with a mandrels' motion shaft of another shaft operatively connected thereto by transmitting and rate transforming mechanism, said latter mechanism being susceptible of producing in said other shaft screw cutting motions, a clutch L operative to connect and disconnect said mandrels' motion shaft and said other shaft, a clutch b operative to connect and disconnect with said other shaft a drive mechanism proper to itself, said latter drive mechanism, and an independently operatable mechanism operative upon said other shaft as a handy jack substantially as described.

31. In a lathe the combination with a mandrels' motion shaft of another shaft operatively connected thereto by transmitting and rate transforming mechanism, said latter mechanism being susceptible of producing in said other shaft screw cutting motions, a clutch L operative to connect and disconnect said mandrels' motion shaft and said other shaft, a clutch b operative to connect and disconnect with said other shaft a drive mechanism proper to itself, said latter drive mechanism, and an independently operatable mechanism operative upon said other shaft as a handy jack substantially as described.

free of said driver or drivers, mechanism operatively controllable to connect and disconnect said carriage and puppet lead screws with said screw motion shaft, mechanism to interconnect or disconnect said carriage and puppet lead screws to each other, and an independently operatable "handy jack" driver engaged with said screw shaft substantially as described.

29. In a lathe the combination of a live stock having mechanism capable of producing a screw cutting rotary motion in one shaft S^5 and in another shaft S^2 a synchronized mandrels' drive motion, a movable mandrels' carriage having a guide part or parts, a guide or guides therefor, mandrels journaled therein and operatively connected to said synchronized mandrels' motion shaft, a tool support or supports adapted to present tools to each of said mandrels simultaneously in similar posture, and mechanism, operative to transmit from said shaft S^5 to said mandrels' carriage motion appropriate to generate simultaneously with the said rotative drive of the mandrels' volute paths substantially as described.

30. In a lathe, the combination with a relatively fixed live stock having a protruding and endwise collared mandrels' motion shaft S^2 , of a movable mandrels' carriage provided with guides and movable in parallelism to said shaft, one or more bearings M' fixed to said carriage, and in conjunction with each bearing M' a bevel gear o^5 , a bevel gear o^4 meshing therewith, and a mandrel driving shaft o^3 to which said gear o^4 is connected, each gear o^5 having an endwise collared hub journaled in the corresponding bearing M' and being splined on the said shaft S^2 .

31. The combination with a sliding lathe mandrel of a yielding abutment and an adjustable stop substantially as described.

32. The combination with a sliding lathe mandrel of a yielding abutment, mechanism for adjustably varying the tension of said yield, and an adjustable stop substantially as described.

33. The combination with a sliding mandrel of a yielding abutment, and a position stop screw substantially as described.

34. In a lathe, a sliding mandrel, a yielding abutment, a face plate fixed to said mandrels' work bearing end and provided with a gear toothed periphery o , a relatively broader spur gear o^2 meshing therewith and an endwise collared shaft o^3 operative to drive said spur gear without detriment to said mandrels' slidings in response to said yielding abutment, substantially as described.

35. The combination with a lathe mandrel of a cranked lever H , a pivotal support therefor, a substantially horizontal arm h^2 , a weight H' adapted to slide along and

bear thereon at any point of its range, a presser collar mounted upon said mandrel, an abutment thereon whereupon said presser collar can preferably with the intervention of a washer bear in opposition to endlong retreats of said sliding mandrel and mechanism for operatively connecting the other or cranked arm of lever H and said presser collar substantially as described.

36. The combination with a lathe mandrel of a cranked lever H , a pivotal support therefor, a substantially horizontal arm h^2 , a weight H' adapted to slide along and bear thereon at any point of its range, a presser collar mounted upon said mandrel, an abutment thereon whereupon said presser collar can preferably with the intervention of a washer bear in opposition to endlong retreats of said sliding mandrel, mechanism for operatively connecting the cranked arm of said loaded lever and said presser collar and stop screw I , substantially as described.

37. In a lathe the combination with a plurality of mandrels operatively driven of a puppet provided in respect to each said mandrel with a plurality of rotative turrets, said turrets being arranged to be movable in series successively to an alinement wherein they severally may be rotated in tool presenting range each of its own proper mandrel and so presenting locked for concurrent action and means for so rotating and locking said turrets.

38. In a lathe, the combination of an operative series of work engaging mandrels, a housing, a tool reel rotatively mounted in said housing, a series of tool supporting turrets, said series of turrets being pivoted on said reel and spaced both in lineal ranks and also in circumferential zones, said zones registering with said mandrels, means for rotating and means for temporarily locking both said reel and each of said turrets at determined angular adjustments on their respective axial supports, and mechanism operative for advancing and retreating said tool supports in range of said mandrels substantially as described.

39. In a lathe, the combination of a movable puppet housing, a guide or guides therefor, and mounted therein a rotatable tool support or supports, said support or supports being provided with polygonal grip parts X X' , bearings p^9 p^{10} fixed to said puppet housing, and, journaled therein, a swinging spanner or spanners x x' , operative when swung in to engage the said polygonal grip parts and thereby for the time of their engagement prevent from rotating said tool support or supports, substantially as described.

40. In a lathe, the combination with a puppet of a rotative tool attaching support, a polygonal grippable part or parts definitely alined thereon in relation to the tool

attachments of said support, and a gripping and locking device consisting of a relatively attached vise spanner or spanners; each said spanner having a relatively fixed jaw, a 5 guide part or parts on said relatively fixed jaw, also thereon a tappet engaging part, x^{10} , and a cam part x^8 , a relatively movable jaw x having a shank bearing on said cam and in part a guide fitting slidingly in the 10 guide parts of said fixed jaw, a rock shaft x^2 journaled to said puppet and whereon said relatively fixed jaw is journaled, a tappet x^{11} fixed to said shaft in described angular relation to cam x^8 aforesaid, and also 15 within operative reach of said relatively fixed spanner jaws' tappet engaging part, and means for rocking said shaft whereby said spanner may be brought to bear and grip on or by a reverse movement released 20 and vibrated away from said gripping part, substantially as and for the purposes described.

41. In a lathe the combination of a plurality of mandrels arranged in line abreast, 25 each operatively driven, a relatively movable puppet, a plurality of adjustably rotative turrets, said turrets being pivoted in sets upon said puppet and also as to each set in a plane alined with the axis of revolution 30 of such set's coöperating mandrel, and mechanical means for adjusting with precision one or more of said turrets transverse the plane of its said set upon the puppet.

42. In a multiple spindle lathe, the combination of a plurality of work spindles, a plurality of axially alined turrets, guides on which said turrets are slideable transversely of their axes, each one into engagement with its corresponding spindle, a grinder arranged on a different side of the turrets from the spindles and a guide extending parallel to the axis of the turrets on which said grinder is slideable.

43. In combination, a plurality of work spindles, a plurality of axially alined turrets, one corresponding to each of said spindles, a supporting frame in which the turrets are held, a sliding support in which the supporting frame is pivotally mounted, 50 guides on which the sliding support is slideable transversely of the axis of the turrets to vary the relation between each spindle and the corresponding turret, a grinder arranged at a different side of the turrets 55 from the spindles, whereby when said supporting frame is rotated the parts may be brought from the operative position relative to the spindles to an operative position relative to the grinder, a guide extending parallel to the axis of the turret on which said grinder is slideable, and means for holding 60 said supporting frame in any desired angular adjustment in said sliding support.

44. In a lathe mechanism the combination 65 of a plurality of mandrels lying in a com-

mon plane, a movable support, a turret carrier operatively connected to said movable support, a plurality of tool engaging mechanisms, said tool engaging mechanisms being connected to said carrier and arranged thereon corresponding to said mandrels in series whereof those proper to each said mandrels is similar to every other, a movable grinding mechanism provided with a guide engaging part, and a guide adapted to define positions of said grinding device in conformity to the serial arrangement of said tool engaging parts, the whole operative to sharpen in conformity and series tools that are at the time of grinding non-active in the 70 lathe mechanism sense, yet held in site by said engaging mechanism, substantially as described.

45. In a lathe the combination of a live stock component, a mandrels' component, a 85 puppet component, a tool grinding component and a bed provided with in respect to themselves relatively fixed guides whereon said mandrels and puppet components have, in relation to each other, a definite 90 movability and whereon also said grinder component has in relation to said puppet a definite movability, graduate points of engagement along said grinder's bed guide, and the described graduate registering set 95 screw w^{50} whereby said grinder may be localized in definite relations with said puppet substantially as described.

46. In a lathe a bed, ways a^4 a^5 formed thereon, carriage M having guide parts m' m^4 registering therewith, a multiplicity of mandrels journaled rotatively therein, tail abutments therefor, work engaging parts O engaged with each said mandrels, means for driving in unison said mandrels, means for 100 presenting as many tools as there are said mandrels within range of their said work engaging parts, the whole operatively concurrently to turn at a single moment as many works as there are mandrels substantially as described.

47. In a lathe a bed, ways a^7 a^6 formed thereon, puppet P having guide feet p^5 p^4 registering therewith, main shaft P' rotatively mounted thereon, reel U, said reel 115 comprising sections as described, and carrying in equal and concentric spacings multiple pin shafts, turrets U', provided with equally spaced and radially alined tool holders mounted in series upon said pin shafts, 120 said series severally conforming in number and alinement with a definite number of co-active mandrels and said mandrels substantially as described.

48. The combination of a bed A having an 125 operating angle as described also frame housings A' A^2 A^3 A^6 , shears A^4 A^5 , ways a^4 a^5 , ways a^6 a^7 transverse to the former ways, and guide A^{10} , live stock mechanism operatively journaled therein, and opera-

tively connectible as described to a prime motor or motors, motion shafts $S^2 S^5 S^7$, lead screws S^{10} and $T T'$, carriage M equipped as described and forming a mandrel's component provided with multiple mandrels, puppet P as described and forming a registering multiple turret bearing support operative as described, said carriage and puppet being provided with registering guide parts mounted on and movable along said ways $a^4 a^5$ and $a^6 a^7$ respectively, a grinder W slidingly guided on guide A^{10} and engageable male and female lock parts affixed to said grinder and guide respectively co-operating upon engagement to positively define sites of activity for said grinder that are in conformity with the tactical arrangement and possible misaligned details of said turreted puppet and operating handles directed toward the operating angle, the whole operative to produce accurately ground and positioned tools and as a corollary thereto work in batches and of precise similarity to sample substantially as described.

49. In a multiple spindle lathe, the combination with the bed and the housing and guide parts adjusted thereto, of the live stock mounted thereon, the mandrels' component and the puppet component mounted on said guide parts and each movable transversely of the line of movement of the other, said mandrels' component having a plurality of mandrels, and said puppet component having one or more tool parts co-operating with each of said mandrels, and positive driving connections between the live stock and the mandrels and puppet components for moving said components on said guide parts and for rotating said mandrels.

50. In combination with a bed, of a live stock, a mandrels' component and a puppet, supported thereon, said mandrels' component comprising a plurality of mandrels, a driving connection from the live stock for rotating each of said mandrels, a driving connection from the live stock for producing relative movement of the mandrels' component and the puppet toward and away from each other, a driving connection for the live stock for producing relative move-

ment of the puppet and mandrels' component transversely to said first mentioned relative movement, said puppet supporting a plurality of tools, one or more co-operating with each spindle, a grinding device and means for bringing it in grinding relation with the tools carried by the puppet co-operating with different mandrels to grind them in predetermined relation each to the other and the several mandrels. 60

51. In a lathe the combination of a plurality of mandrels arranged in line abreast, bearings for said mandrels, a guide or guides, a movable housing having a guide or guides, means for so moving said housing, a reel rotatively connected to said housing, means for rotating said reel, means for fixing the same at designated points of angular adjustment in relation to said housing, multiple tool holding turrets registering with 70 said mandrels and rotatively connected to said housing, and means for fixing the same at designated points of adjustment in relation to said reel whereby they may extend successive series of tools to each said mandrels substantially as described. 75

52. In a lathe the combination of a plurality of similar mandrels arranged in line abreast, bearings for said mandrels, a guide or guides parallel to the line of said mandrels, a grinder having a guide or guide's part adapted to register with and move along said guide, also operative points along said guide or guides, mechanical means secured to said grinder and controllably engageable with said operative points, a guide or guides and a housing having a guide part or parts to register therewith and move thereon reciprocally between said mandrels and said grinder, multiple tool holding parts 90 mounted rotatively and in series corresponding to said mandrels in said housing and operative, when advanced, simultaneously to extend tools to each said mandrels, and, when retreated to extend tools, in reverse, to 95 said grinder, substantially as described.

ANTON CHRISTENSEN.
